UNITED STATES PATENT OFFICE.

HARRY G. WEBSTER, OF CHICAGO, ILLINOIS, ASSIGNOR, BY MESNE ASSIGNMENTS, TO
JAMES R. GARFIELD, TRUSTEE, OF CLEVELAND, OHIO.

TELEPHONE-EXCHANGE SYSTEM.

1,252,974.

Specification of Letters Patent. Patented Jan. 8, 1918.

Application filed May 16, 1914. Serial No. 838,961.

To all whom it may concern:

Be it known that I, HARRY G. WEBSTER, a citizen of the United States, residing at Chicago, in the county of Cook and State of Illinois, have invented a new and useful Improvement in Telephone-Exchange Systems, of which the following is a specification.

My invention relates to telephone exchange systems, and particularly to that type of automatic systems in which the line of a calling subscriber is automatically extended to the position of an idle operator who is provided with key board mechanism for directly controlling automatic switching mechanism for building up a connection extending to the line of the subscriber desired. It relates also to multi-exchange systems in which calls originating in one exchange are completed by means of trunk lines extending to the other exchanges of the system. In prior multi-office systems employing manual operators, it has been the practice to provide operators technically known as "B" operators, connected by instruction circuits with those operators who answer calling subscribers, and to equip the trunk lines with manual terminals or plugs by means of which the "B" operators could connect idle trunk lines with the lines of called subscribers upon receiving verbal instruction from the answering operators. One object of the present invention is the elimination of the so-called "B" operators with the plug-ended trunks and instruction circuits, and instead, to provide means for completing calls between exchanges by means of automatic switching mechanism controlled by operator's key board apparatus.

A further object of my invention is the provision of automatic switching mechanism such that certain exchanges of a multi-office system may give service without the employment of operators located at the exchange, being entirely controlled by operators located at some other exchange, or at a distant point. This feature of my invention also provides means whereby calls originating and terminating in the same unattended exchange may be completed without involving in the talking circuit connecting the subscribers, trunks extending to another exchange.

55 A further object of my invention looks to

an increase in the total line capacity of systems employing a series of automatic switches for completing connection between a calling and a called subscriber. In prior systems of this kind, for example, a five digit system, it has been possible to use only those call numbers comprising five digits each and beginning with the numerals one to nine, inclusive. Call numbers consisting of one, two, three and four digits have not been heretofore utilized in a five-digit system, and the line capacity of such systems has therefore been to this extent limited. It is one feature of the present invention to provide means for utilizing those call numbers having fewer digits than the maximum number of digits employed in the system, thus materially increasing the total line capacity of the system.

My invention also comprises certain improvements with respect to circuit arrangement, and other details which, together with the above, will be more fully explained in the following description taken in connection with the accompanying drawings.

In accordance with the particular embodiments of my invention here illustrated, the line of a calling subscriber is extended to the keyset operator (who manipulates the keys controlling the switches for building up the complete connection) by three selective operations which I shall characterize as "primary," "secondary" and "tertiary" selections. In one embodiment the primary selection is performed by the answering or "A" operator of a manual exchange using the ordinary answering cord pair. In another embodiment also here described, the primary selection is accomplished by a related group of so-called tens and units relays arranged generally in the manner described in Patent No. 1,091,193 issued to Edward E. Clement March 24, 1914. In each case the secondary selection is accomplished by a similar relay group associated with an intermediate trunk. The secondary selection serves to select and connect to an intermediate trunk a first selector which has been associated with the called subscriber's line as a part of the primary selecting operation. The tertiary selection is performed by a similar relay group which is directly associated with a keyset. The tertiary selection serves to select an intermediate trunk which has been connected with a first selec-

tor, and to connect it directly with a keyset. This connection is followed by the display of a calling signal before the particular operator in charge of the so connected keyset.

- 5 The series of switches for extending the calling subscriber's circuit to that of the called subscriber are directly controlled by the keyset apparatus; and comprise second selectors, third selectors and connectors, 10 in the particular five digit system here described. The first selector serves to pick a trunk leading to a distant exchange and terminating in a second selector, to be hereinafter referred to as an "inter-office selector." 15 The inter-office selector serves to pick a local trunk terminating in a third selector, to be hereinafter referred to as a "local selector." The local selector serves to pick a trunk leading to a connector associated with the 20 line group containing the called subscriber's line; and the connector serves to pick the desired line and to automatically apply current to ring the bell at the sub-station in case the desired line be idle. The first 25 selector may also pick a local selector, serving as a second selector, located within the originating exchange.

Referring now to the drawings, Figure 1 illustrates an "A" operator's apparatus, and 30 line circuit arrangement which may be used in case the primary selection is performed by an "A" operator. Fig. 2 illustrates the the first selector to which the calling line is connected by the "A" operator. Fig. 3 illustrates the inter-office selector, Fig. 4 the local selector, and Fig. 5 the connector. Fig. 6 shows the arrangement of the tens and units relays for performing the secondary selection, and Fig. 7 the secondary 40 control apparatus for controlling and guarding the secondary selecting operation. Fig. 8 illustrates a section of the intermediate trunk with which the grouped relays of Fig. 6 are associated, and also the apparatus for controlling and guarding the tertiary selecting operation. Fig. 9 illustrates the grouped relays associated with each keyset for accomplishing the tertiary selection, together with switching apparatus for guarding 50 against delay in case a keyset becomes disabled; and Fig. 10 shows the complete group of keyset apparatus with which the group of tertiary selecting relays is associated.

55 Figs. 11, 12 and 13, in connection with Figs. 8 to 10, inclusive, illustrate that modification of my invention in which the primary selection is performed by relay groups rather than manually by an "A" operator. 60 Fig. 11 shows a subscriber's line circuit and the relay group for selecting a calling line. Fig. 12 shows the apparatus for controlling and guarding the primary selecting apparatus of Fig. 11, and Fig. 13 shows the first 65 selector associated with the relay group of

Fig. 11, and which is thereby connected with the calling line. Figs. 14 and 15 illustrate a modification of the tertiary selection and keyset apparatus, whereby calls originating and terminating within the same sub-ex- 70 change may be established using talking trunks entirely local to such exchange. Fig. 16 is a diagram illustrating a method of arranging a plurality of keysets in related sub-groups for the use of a plurality of key- 75 set operators. Fig. 17 is a diagram illustrative of my invention as embodied in an ex- change system comprising five main ex- changes and two sub-exchanges, wherein the keyset operators are all located at the cen- 80 tral main exchange. Fig. 18 is a chart show- ing the proper manner of relating the drawings 1 to 10, inclusive, to illustrate the arrangement in which the primary selection is performed by "A" operators; and Fig. 19 85 is a similar chart showing the arrangement of the drawings for illustrating the modifi- cation in which the primary selection is auto- matically performed by relay groups.

Referring first to the traveling switches 90 indicated in the accompanying drawings, the selectors and connectors are of that type in which the switch wipers are first direc- 95 tively driven in a rotary direction until opposite the elected group of contacts; and are then driven in a vertical direction with the wipers in engagement with the bank contacts. In the selectors, the vertical stepping is automatically controlled to bring the wipers to rest when an idle set of bank contacts is reached; while in the connectors, the vertical travel is directly controlled to 100 select an elected set of bank contacts. In the selector switches there are eleven sets of bank contacts in each vertical row, while in the connectors there are but ten sets, these constituting the terminals of called lines. The mechanical structure of a suitable switch for practising my invention is de- 105 scribed in Patent No. 977,536, issued to C. H. North December 6, 1910, although my in- 110 vention is not limited to this particular switch mechanism.

The first selector switch is indicated in Fig. 2 by the wipers b_{52} , b_{53} , b_{54} , with 115 their associated bank contacts, and the rotary driving magnet b_{20} , the vertical mag- net b_{21} , and the release magnet b_{22} . A rotary off-normal contact set is indicated at b_{25} ; and is actuated at the first rotary step 120 of the switch and restored to normal at the end of the rotary restoring motion of the switch. Vertical off-normal contact sets are indicated at b_{50} and b_{51} , these being actu- ated at the first vertical step of the switch 125 and restored at the end of the vertical re- storing motion thereof. The inter-office se- 130 lector is indicated in Fig. 3 of the drawings by the rotary driving magnet b_{20} , the verti- cal magnet b_{21} , the release magnet b_{22} , the

wipers h_{52} , h_{53} , h_{54} , with the associated bank contacts, the rotary off-normal contact set i_{25} , and the vertical off-normal contact sets i_{51} and i_{52} . The local selector is indicated in Fig. 4 by the rotary magnet i_{20} , the vertical magnet i_{21} , the release magnet i_{22} , the wipers and bank contacts at i_{52} , i_{53} , i_{54} , the rotary off-normal contact set i_{25} , and the vertical off-normal contact sets i_{50} and i_{51} . The connector switch is indicated in Fig. 5 by the rotary driving magnet j_{20} , the vertical magnet j_{21} , the contact banks and wipers j_{52} , j_{53} , the rotary off-normal contacts j_{25} , and the vertical off-normal contact sets j_{50} and j_{51} . In Fig. 13, the first selector switch is indicated by the rotary driving magnet t_{20} , the vertical magnet t_{21} , the release magnet t_{22} , the rotary off-normal contacts t_{25} , the vertical off-normal contact sets t_{50} and t_{51} , and the bank contacts and wipers t_{52} , t_{53} and t_{54} .

In addition to the selector and connector switches above mentioned, I employ, in practising my invention, a number of traveling switches of that type in which the wipers are stepped with a rotary motion only, and always in the same direction. These switches are driven with a step-by-step motion, being stepped forward one step on each retraction of the armature of the driving magnet. The wipers are not spring restored as in some types of rotary switches, but are stepped forward by the action of the driving magnet until the normal position is reached.

35 Patent No. 988,390, issued to F. Schoenwolf April 4, 1911, indicates a suitable mechanical construction for the switches of this type, it being understood that the driving pawl and armature are to be arranged to move the switch wipers on the retraction of the driving armature rather than on its attraction. Also, I have indicated my switch wipers as provided with two extending arms rather than with three arms as shown in the patent 40 just referred to. It will, of course, be understood that my invention is not limited to this particular form of switch, but that any suitable switch mechanism may be substituted therefor.

50 In Fig. 7 of the drawings, I have indicated at D a ten-point rotary switch of the kind just described having a driving magnet d_{20} and three sets of wipers and bank contacts indicated at d_{60} , d_{61} , and d_{62} . In 55 Fig. 8, I have indicated at D1 a ten-point rotary switch having the driving magnet e_{20} , and two sets of wipers and bank contacts indicated at e_{60} , and e_{61} . In Fig. 9, I have indicated at D2 a similar ten-point rotary switch having the driving magnet f_{20} with three sets of wipers and bank contacts as indicated at f_{37} , f_{38} and f_{39} ; and in addition, this switch is provided with a contact set indicated at f_{40} . The contacts of 60 this set occupy the position indicated when

the switch wipers are in the normal position as shown in the drawing, the lever spring being moved manually to the alternate position when the switch wipers are off-normal, and remaining in such alternative 70 position until the wipers are again restored to the normal point. In Fig. 10, I have indicated at D4 a twelve-point rotary switch having the driving magnet g_{20} , and three sets of wipers and bank contacts indicated 75 at g_{47} , g_{48} and g_{49} . In this same figure, at D5 I have shown a second twelve-point rotary switch having the driving magnet g_{21} and two sets of wipers and bank contacts indicated at g_{50} and g_{51} . In Fig. 12, 80 I have indicated at D3 a ten-point rotary switch having the driving magnet g_{20} and three sets of wipers and bank contacts g_{60} , g_{61} and g_{62} .

With respect to all of the switches above 85 mentioned, these are shown in the drawings with the switch wipers in that position occupied by the switch when it is at normal.

Referring again to Fig. 10, I have indicated at g_{41} a strip or row of ten keys 90 adapted for separate actuation by means of numbered finger buttons. The strip of keys is provided with a common locking means so arranged that upon actuation of a key it will be locked in the actuated position until 95 released by the subsequent actuation of another key. The buttons are to be understood as being numbered from 1 to 0, beginning with the lowest key of the strip. A suitable mechanical arrangement for this strip 100 of keys is described in Patent No. 991,590, issued to J. L. Wright May 9, 1911.

Similar strips of keys associated with that just described are indicated at g_{42} , g_{43} , g_{44} and g_{45} . In addition, strips g_{42} , g_{43} 105 and g_{44} are to be understood as provided with releasing means, indicated at g_{99} , so arranged that when the circuit of magnet g_{22} is closed by the actuation of answering key g_{25} , the locking mechanism of each of 110 these strips will be operated to release any previously actuated keys in these strips. In the system here described, the five strips of keys correspond to the five digits employed 115 as the maximum number in the subscriber's call numbers of the system. The left-hand strip corresponds to the first digit or to the exchange name of the call number. The strip g_{42} corresponds to the thousands digit 120 of the call number, the strip g_{43} to the hundreds digit of the call number, and the strips g_{44} and g_{45} to the tens and units digits, respectively, of the call number. The keys g_{25} , g_{26} and g_{27} are manually actuated keys located before the operator adjacent to the strips of keys g_{41} , g_{42} , g_{43} , g_{44} and g_{45} , and to the lamps g_{23} , g_{24} and g_{35} . The functions of these keys and lamps will 125 be brought out in the subsequent description of their operation.

The connector switch indicated in Fig. 5 is provided with an auxiliary switch individual thereto, employed in connection with the application and removal of ringing current to operate the call signal at the substation of the desired line. This ringing switch comprises the driving magnet j_{16} , provided with a driving pawl engaging at each retraction of the magnet armature with the teeth of a ratchet wheel fixed to a driving shaft. This driving pawl is indicated at j_{99} . Secured to the same driving shaft is a series of cams j_{31} , j_{32} , j_{33} , j_{34} , j_{35} , j_{36} and j_{37} . With each cam is associated a pair of contact springs, as indicated. At each deenergization of the magnet j_{16} , the driving shaft and cams are advanced a distance corresponding to one tooth of the ratchet j_{99} , and serve to control the contact springs in a manner to be hereinafter described in detail. Current to energize the transmitter of the called subscriber is furnished from the central battery through the winding of relay j_{10} on one side of the talking circuit, and through the cut-off relay of the called line on the opposite side of the talking circuit.

Referring now to my invention as embodied in the system indicated by Fig. 18 of the drawings, Fig. 1 illustrates at A, B well-known cord and line circuit apparatus in a manual exchange of a multi-office system. This exchange may be assumed to be equipped for approximately 10,000 subscriber lines. A call originating at substation B may be completed to a called station C located within the same exchange by means of the cord circuit and multiple jacks illustrated in the figure in the customary manner which will be well understood without further description. Calls originating at the calling station B and terminating at other exchanges of the system are to be completed by means of a calling plug G and the trunk jacks shown at the right of the drawing. Each operator of the manual exchange is assumed to be provided with a plurality of trunk jacks, five being illustrated, and each of these trunk jacks is directly connected to the circuits of a first selector illustrated in Fig. 2 of the drawings. Assuming that the outgoing traffic of the exchange under consideration requires a total number of 500 such first selectors, these may then be sub-divided into groups of 100 first selectors, and each "A" operator would preferably have access to at least one first selector in each group by means of trunk jacks as illustrated in Fig. 1. These jacks might be preferably so spaced in the panels of the manual multiple switch-board as to proportion ten jacks to each three operators but placing a total of ten jacks within reach of any one operator.

Assuming that the five-hundred first se-

lectors of the system are divided into sub-groups of one-hundred each, there would then preferably be a group of intermediate trunks associated with each one-hundred first selectors. The number of intermediate trunks in each group would be proportioned to the traffic originating in the one-hundred first selectors associated therewith, ten for example. There would thus be a total of fifty intermediate trunks for the five-hundred first selectors. Each intermediate trunk has a group of tens relays, ten in number, two of which are shown at c_1-c_3 , Fig. 6, and a related group of units relays, also ten in number, two of which are indicated at c_2-c_4 , Fig. 6. The tens relays are each provided with contact points corresponding to ten of the first selector switches of the associated sub-group, and the units relays are each provided with contact points corresponding to one first selector in any ten. The relation between the terminals of a sub-group of first selectors and the tens and units relays of each of the intermediate trunks associated therewith is such that the energization of a particular tens relay and a particular units relay of an intermediate trunk will be brought about through a control exercised by a particular first selector and will result in the connection of that first selector with the intermediate trunk to which the tens and units relays belong, and the exclusion therefrom of the other first selectors of the sub-group during the existence of the connection just described. This method of selection is described generally in Patent No. 1,091,193 previously mentioned, to which reference may be made in connection with the description to be made of the detail of operation of the particular arrangement of controlling circuits shown in the present application. By means of its tens and units relays, each intermediate trunk of a group of ten may thus select and connect with any one of the one-hundred first selectors in the sub-group with which the group of intermediate trunks is associated.

Each intermediate trunk extends by three conductors e_{35} , e_{25} and e_{34} , Fig. 6, to the point at which the tertiary selecting apparatus is located. This apparatus is shown in Figs. 8, 9 and 10, and in the system of the present description is located at the most central of the several exchanges of the multi-office system. That portion of trunk conductors e_{35} , e_{25} and e_{34} , extending between Figs. 6 and 8, may be made of any desired length. The first selectors of an outlying exchange may therefore be several miles or more distant from the centrally located exchange at which the tertiary selecting apparatus is placed.

At the tertiary selecting end of the intermediate trunks, all such trunks in the sys-

- tem may be regarded as a single group. A sufficient number of operator's keysets are associated with this group to handle the total traffic of the system, and each keyset is provided with a group of related tens and units relays of sufficient size to enable any keyset to select and connect with any intermediate trunk of the system. The relation and operation of these relays is the same as that of the corresponding relays for the secondary selection. The keysets are preferably subdivided into sub-groups of three, so arranged that each sub-group is accessible to and controlled by a single keyset operator.
- 10 The controlling circuits are such that the operators' positions and keysets are sequentially related, and when a calling line is extended to an intermediate trunk, this intermediate trunk is then selected by the first 15 idle keyset of the first operator's position in the sequence at which no call lamp is then burning.
- 15 The controlling circuits are such that the operators' positions and keysets are sequentially related, and when a calling line is extended to an intermediate trunk, this intermediate trunk is then selected by the first 20 idle keyset of the first operator's position in the sequence at which no call lamp is then burning.

Referring again to the first selectors, the bank contacts of these switches constitute the terminals of trunks leading to the principal divisions of the system. Those trunks leading to that division having the same geographical location as the first selectors terminate in local selector switches arranged 25 as in Fig. 4, and functioning as second selectors. The groups of bank contacts on these second local selectors represent the different thousands of the exchange in which the first selectors are located. The trunks which lead 30 from the first selector banks to exchange or divisions of the system of different geographical location from the first selectors terminate in inter-office selectors arranged as illustrated in Fig. 3, and functioning as 35 second selectors in the system. The groups of bank contacts of these inter-office selectors represent the different thousands of 40 the exchange in which they are located.

The trunks leading from the bank contacts of the inter-office selectors and from the bank contacts of the local selectors functioning as second selectors, each terminate in local selector switches arranged as in Fig. 4, and functioning as third selectors in the 45 system. The groups of bank contacts of these local selectors represent the different hundreds of the particular thousand to which the local selector corresponds. The trunks from these bank contacts lead to connectors arranged as illustrated in Fig. 5 of the drawings. A group of such connectors is provided for each one-hundred lines of the system, there being a sufficient number of connectors in each such group to care for the maximum number of calls terminating in the one-hundred line group at any time; and the connectors serve to select the terminals of a called line and to automatically apply ringing current if the desired line 55 be idle.

The general arrangement of a multi-exchange system like that above described is illustrated in Fig. 17 of the drawings. In this drawing is indicated a system having five principal exchanges—N, S, E, W and 70 M, located at points geographically separate. Each of these exchanges is provided with manual operator's equipment, including cord pairs indicated at A for answering calls originating at calling lines B, and with 75 trunks leading to first selectors F corresponding to those indicated in Fig. 2 of the drawings. Each exchange also includes second selectors H, third selectors I, and connectors J, these all being understood to be 80 provided in the customary number and grouping suitable for a capacity of ten-thousand lines at each exchange. The keysets and associated apparatus of Fig. 10 are located at the exchange M, which is assumed 85 to be the most central of the system, and are indicated at Q. The tertiary selecting apparatus is also located at this exchange, and is indicated on the drawing by the symbol at L. The secondary selecting apparatus indicated at K is located at each exchange; and the groups of intermediate trunks leading 90 from the point of secondary selection to the point of tertiary selection are indicated by the heavy lines Y.

As illustrated by Fig. 17, a call originating at a line B, for example, at the S exchange, will be answered by the operator's equipment A at S, and, if for a subscriber within the S exchange, may be completed by 100 the answering operator at A plugging into a multiple jack of the desired line. If, however, the call is for a subscriber at exchange N, the operator A at exchange S extends the calling line to an operator at Q by means of 105 the jack a16 and the secondary selecting apparatus K, an intermediate trunk Y, and tertiary selecting apparatus L. Upon response of the operator Q, the call number of the desired line is given and the operator 110 Q then sets the keys of the selected keyset to correspond to the call-number and then actuates the start button. Assuming the call number to have been N—3311, the pressing of start button is followed by the automatic 115 operation of first selector F at S to select an idle second selector in the group H at N; the automatic operation of H to select an idle third selector in the group I at N; the automatic operation of the third selector to 120 select an idle connector in the group J at N; and the automatic operation of the selected connector to pick and ring the called line C at N. The selection of the called line C is immediately followed by the release and 125 disconnection at L and at K in the S exchange of the intermediate trunk Y used in extending the call to the operator at Q. The calling subscriber B at S may now converse with the called subscriber C at N over 130

the circuit extending through the cord pair A and first selector F at S, and the second selector at H, third selector at I, and connector at J of exchange N. The connection thus established is automatically released and all switches restored to normal at the conclusion of the conversation; and the supervisory signals associated with the cord pair at A of the S exchange indicate to the answering operator that she may restore the cord pair and thus the normal condition of the calling line B.

In association with the N exchange of Fig. 17, two sub-exchanges are indicated at N—3300 and N—2400. The relation of these exchanges to the entire system will be explained in describing that modification in which the primary selection of the calling line is performed automatically rather than by an A operator. It is to be pointed out with respect to Fig. 17 that in each of the exchanges, as for example S, a call originating and terminating within the exchange may be completed under control of an operator at Q by means of the jack a16 and the first selectors F, second selectors H, third selectors I and connectors J, all within the exchange. It will also be evident that this may likewise be equally accomplished when the calling line B is associated with a first selector F as the result of automatic primary selection.

I will now describe in detail the operation of the apparatus used in the establishment of a connection from a calling subscriber in one exchange to a called subscriber in a distant exchange, using the various drawings indicated on the chart Fig. 18. In these drawings, as well as in the others forming part of this application, it is to be understood that each exchange is provided with its own central battery common to the circuits of such exchange in the manner well known to the art. In order to simplify the drawings, the symbol indicating such central battery has been frequently repeated throughout the drawings, and is to be understood as indicating the central battery of the exchange within which the apparatus shown in association therewith is located. Before describing the operations following the initiation of a call, it will be necessary to describe in detail the apparatus by means of which the secondary and tertiary selections are controlled.

Considering a group of one-hundred first selectors, these are to be regarded as numbered from 0 to 99, inclusive, the relation being the same as that described for a group of one-hundred sub-station lines in Patent No. 1,091,193. Each first selector is provided with a relay corresponding in function to the line relay M of the patent just mentioned. This relay for the first selector Fig. 2 is shown at d1 in Fig. 7, and the first

selector is to be understood as being numbered 11 in its group. Other first selectors are indicated by the corresponding relays d2, d11 and d12, Fig. 7, and these other first selectors are those numbered 12, 21 and 22, respectively. Each first selector is provided with a cut-off relay b5 serving to interrupt the circuit of relay d1, corresponding in this function to the cut-off relay M' of Patent No. 1,091,193. Regarding the first selectors as sub-divided into groups of ten in accordance with the tens digit of their respective numbers then, for example, those numbered 10 to 19, inclusive, would be in one sub-group, those numbered 20 to 29, inclusive, in another sub-group, and so on. Each sub-group has a relay d13 serving to hold normally interrupted that wire leading from the right hand contact of each of the relays d1, which wire corresponds to the units digit of the first selector number.

The entire group of one-hundred first selectors is provided with a group of ten relays which may be known as the tens series group. This group of relays is indicated in Fig. 7 at d5, d6 and d7, those at d5 and d6 being the first two of the series of ten, and that at d7 the last one of the series of ten. The relay d5 relates to the sub-groups of first selectors numbered 10 to 19; the relay d6 relates to the sub-group of first selectors numbered 20 to 29, inclusive, and so on; each relay of the tens series group thus corresponds to a particular tens digit in the numbers of the first selectors in a group of one-hundred. Another group of relays to be known as the units series group is likewise associated with each group of one-hundred first selectors. The relays d8 and d9, Fig. 7, are the first two relays of this group of ten, and the relay d10 is the last one of the series. The relay d8 is related to all first selectors having the numeral 1 as the units digit of its number; the relay d9 is related to all first selectors having the numeral 2 as the units digit of its number, and so on. Each of the units series group of relays therefore corresponds to a different numeral of those used as the units digits in the numbers of the first selectors of a group of one-hundred. A relay d3 is associated with the tens series group, and a relay d4 is associated with the units series group, the functions of these relays being brought out in the subsequent description. The relays so far described with respect to Fig. 7 are related to and provided for each group of one-hundred first selectors.

In Fig. 6 I have indicated a group of ten intermediate trunks. These trunks are serially related, and in the normal position of the switch D, Fig. 7, the first trunk of the group is that indicated as having the conductors e35, e25 and e34, Fig. 6. Assuming a group of one-hundred first selectors, each

trunk is provided with ten units relays, two of those of the first intermediate trunk being shown at $e2$ and $e4$. Each trunk is also provided with ten tens relays, two of those for the first intermediate trunk being shown at $e1$ and $e3$. Each intermediate trunk also has a relay $e5$ which by its momentary operation causes the energization of the proper tens relay and the proper units relay of the trunk to select and connect the desired first selector. Each intermediate trunk is also provided with a relay $e8$, and with a slow acting relay $e9$ whose functions will be subsequently explained. The second intermediate trunk of the group is indicated by the relays $e6$, $e10$ and $e11$ corresponding respectively to the relays $e5$, $e8$ and $e9$ of the first intermediate trunk. Respectively corresponding relays $e7$, $e12$ and $e13$ indicate the last intermediate trunk of the group, the wire which serially relates to ten trunks being indicated by the symbol at $e50$ as extending through the relays of the trunks of the group not actually shown. The same group relation is indicated at the bank contacts and wipers $e62$ of the rotary switch D, Fig. 7, the wipers standing on the contact of the first trunk, and the bank contacts for the entire group of intermediate trunks being shown. The complete group of tens series relays for the group of one-hundred first selectors is similarly indicated at the bank contacts and wipers $e60$ of the switch D; and the group of units series relays by the bank contacts and wipers $e61$. The relation of the intermediate trunks at the point of tertiary selection and the controlling apparatus therefor is like at the point of secondary selection.

As illustrated in Figs. 8, 9 and 10, each intermediate trunk is provided with a relay $e1$ corresponding in function to $d1$ of Fig. 7, and with a relay $e19$ corresponding in function to $b5$ of Fig. 2. The entire number of intermediate trunks in an exchange system may be regarded as a single group divided into sub-groups. For the purpose of this description, it may be assumed that there are one-hundred intermediate trunks, and that these are numbered and sub-divided in groups of ten in a manner corresponding to that already described for the group of one-hundred first selectors. It is to be understood, however, that the entire number of intermediate trunks may be greater or less than one-hundred, and that the number of intermediate trunks in each sub-group may be likewise modified without changing the method of operation here described. Referring to Fig. 8, I have indicated four intermediate trunks represented by the relays $e1$, $e2$, $e11$ and $e12$, and these intermediate trunks may be understood as numbered 11, 12, 21 and 22, respectively. A group of tens series relays corresponding to that of Fig. 7 is indicated at $e5$, $e6$, $e7$; and a group of units series relays corresponding to that of Fig. 7 is indicated at $e8$, $e9$, $e10$. The relay $e3$ corresponds to $d3$, and the relay $e4$ corresponds to $d4$. The switch $D1$ differs from the switch D of Fig. 7 in that it is provided with but two sets of bank contacts and wipers. The wipers and contacts $e60$ correspond to those at $d60$ of Fig. 7; and those at $e61$ correspond to those at $d61$ of Fig. 7.

In Figs. 9 and 10 I have indicated a plurality of keysets. These are to be regarded as a single group of sufficient number to handle the maximum traffic of the system. The keysets are serially related, the first keyset of the series being indicated as provided with a group of tens relays $f1$, and with a group of units relays $f2$, and otherwise the circuits of this keyset are shown in complete detail. In the present instance each keyset would have ten of the relays $f1$ and ten of the relays $f2$, the relation between them and the group of one-hundred intermediate trunks being the same as that previously described for the tens and units relays of the intermediate trunk and the group of one-hundred first selectors. Each keyset is provided with a relay $g11$ corresponding in certain respects to relay $e8$ of the intermediate trunk, and with a relay $f5$ corresponding to relay $c5$ of the intermediate trunk. The second and third keysets of the group are indicated respectively by the relays $f6$ and $f7$ corresponding to relay $f5$ of the first keyset, and also by the wire $g33$ which is to be understood as extending to the left hand contact lever of a relay corresponding to $g11$ associated with the next keyset in the series, and so on through the entire group. The group of keysets is to be understood as subdivided into sub-groups of three corresponding to the several operators' positions, as will be more fully explained in connection with the diagram of Fig. 16; and the lower set of bank contacts of the rotary switch $D2$ provides one bank contact $f39$ for each operator's position. It is further to be pointed out that the intermediate trunks are preferably so numbered that the trunks of a sub-group serving a particular group of one-hundred first selectors each have a different tens digit numeral and are thus selected and connected each by a different tens relay in the group of tens relays for any keyset. By this arrangement of numbering, I prevent the tying up of any sub-group of intermediate trunks in case of faulty operation of a tens relay at the keyset. The relation and operation of the apparatus indicated in Fig. 8 corresponds to that of the apparatus for Fig. 7 except as hereinafter pointed out.

Referring first to Fig. 1, it will be assumed that the subscriber at station B, whose

group of units relays is connected to the subscriber at station A, the subscriber at station B, whose

line is indicated at 21, is the calling subscriber and is located at exchange W. The removal of the receiver at B energizes relay a_1 by current flowing through the normally closed contact and windings of relay a_2 , thereby closing the circuit of lamp a_{21} causing its illumination. The operator whose telephone is indicated at A thereupon inserts the plug P in the jack a_{22} , energizing relays a_2 , a_5 and a_6 . Relay a_2 in operating releases relay a_1 thereby extinguishing lamp a_{21} ; while the operation of relay a_6 , by current flowing through the sub-station transmitter, prevents the illumination of lamp a_{12} . The operation of the apparatus up to this point is well-known to those skilled in the art. Assuming the call-number of the desired line to be South 3456 and the desired line to be therefore in the S exchange, the operator, before restoring her listening key, inserts the calling plug G into an unoccupied jack a_{16} accessible from her position. This operation initiates the secondary selection by closing the local contact of jack a_{16} , completing a circuit leading from ground through wire b_{28} and winding of relay b_6 to battery. The energization of relay b_6 completes a circuit leading from ground through the normally closed contact of rotary off-normal springs b_{25} , right hand contact of relay b_6 , normally closed contact of b_{13} , upper contact of relay b_{12} , lower contact of relay b_5 , and through wire b_{29} , Figs. 6 and 7, to battery through the winding of relay d_1 . Relay d_1 is energized closing circuit from ground through its center contact lever, the left hand contact of relay d_3 , the winding of relay d_5 , wire d_{25} , and the upper contact of relay d_{18} to battery. Relay d_5 is thereby energized closing a locking circuit in shunt of the left-hand contact of relay d_3 by its center contact lever, and closing a circuit from ground through its left-hand contact and the winding of relay d_3 to battery. Relay d_3 is thereby operated, opening the circuits leading to the several relays of the tens series group, relay d_5 , however, remaining energized by reason of the locking circuit first closed. The operation of the right hand contact lever of relay d_5 closes a circuit from ground through the wiper and normally resting contact at d_{60} , through the normally open right hand contact of relay d_5 , and the winding of relay d_{13} to battery. The energization of relay d_{13} now closes a circuit leading from ground through the right hand contact of relay d_1 , the left hand contact of relay d_4 , and the winding of relay d_8 to battery, through wire d_{25} and the upper contact of relay d_{18} . The resulting energization of relay d_8 closes its locking circuit in shunt of the left hand contact of relay d_4 by means of its middle contact lever, and closes another circuit leading from ground through its left hand con-

tact lever and the winding of relay d_4 to battery. The energization of relay d_4 breaks the circuits leading to the several relays of the units series group, relay d_8 , however, remaining energized by reason of its locking contact. Relay d_8 , by the operation of its right hand contact lever, has closed a circuit leading from ground through the wiper and normally resting contact of switch D at d_{61} , the right hand armature lever and forward contact at d_8 , and through wire d_{27} to the center contact point of each of the relays c_5 , c_6 and c_7 . It is to be here noted that the previous energization of relay d_{13} has closed a circuit leading from ground through its right hand contact points to the extreme left hand contact point of each of the relays c_5 c_6 and c_7 .

From the operation so far described, it will be seen that the energization of relay d_1 has resulted in the operation of the number 1 relay of the tens series group (d_5), and of the number 1 relay of the units series group (d_8), and that the operation of d_5 has resulted in the placing of ground on that contact of relay c_5 corresponding to the number 1 tens relay of the intermediate trunk, and that the operation of d_8 has resulted in the placing of ground on that contact of c_5 corresponding to the number 1 units relay of the corresponding intermediate trunk. The connection from ground at the left hand contact of relay d_8 also closes a circuit leading from this point through the wiper and bank contact at d_{62} corresponding to the first intermediate trunk of the group serving the group of first selectors in which is included the first selector of Fig. 2. This circuit extends through wire d_{26} , normally closed contact of relay c_8 , and the winding of relay c_5 . The energization of relay c_5 , by reason of the ground previously placed on its left hand and middle contact points, energizes relay c_1 and relay c_2 , thus connecting the talking wires e_{35} and e_{34} of the intermediate trunk to the talking wires b_{35} and b_{34} of the first selector of Fig. 2. This first selector is number 11 in its group of one-hundred. At the same time, the closing of the local circuit wire b_{31} associated with these talking conductors, completes a circuit leading from battery through the winding of c_8 , the contacts of relay c_2 and c_1 , wire b_{31} , winding of relay b_5 upper contact of relay b_{12} , normally closed contact of relay b_{13} , right hand contact (now closed) of relay b_6 and to ground through off-normal springs b_{25} . Relay c_8 , by the operation of its middle contact lever, closes a locking circuit for relay c_1 leading from ground through the non-inductive resistance c_{21} to the lower contact point of relay c_1 , and a locking circuit for relay c_2 leading from ground through the non-inductive resistance c_{22} and the lower contact point of relay c_2 . Relay c_1 and c_2 are connected in series with the talking wires e_{35} and e_{34} of the intermediate trunk.

c9 has been previously energized by the circuit closed from ground through the right hand contact of relay c5 and the winding of relay c9 to battery. The operation of the 5 left hand contact lever of relay c8 interrupts the circuit of relay c5 and extends the wire d26 through to the contact lever of relay c9 which, however, is a sluggish relay and maintains its energization for a sufficient 10 time to hold the circuit of wire 26 open at its contact until ground is removed from the circuit of this wire through the deenergization of relay d8. The result following the 15 closing of the right hand contact of relay c8 will be described in connection with the tertiary selection. The energization of relay b5 over the circuit including wire b31 20 interrupts at its lower contact the original energizing circuit for relay d1 through wire b29. Relay d1 drops back interrupting at its middle contact the circuit of relay d5, and at its right hand contact the circuit of relay d8. Relay d5 in dropping back 25 interrupts the circuit of relays d13 and d3; while relay d8 in dropping back interrupts the circuit of relay d4 and removes ground from the wire d26. The dropping back of relay d13 removes ground from the left hand contact of relay c5, and the dropping back of 30 relay d8 removes ground from the center contact of relay c5. The operation of relay b5 has connected talking wire b34 with that portion of the talking circuit of the first selector extending to the jack a16 35 through condenser b42 and conductor b24. The controlling apparatus of the secondary selection is thus restored to normal and ready for the initiation of another secondary selection involving a different first selector 40 and intermediate trunk. The operation as so far described has occupied a time interval of but a small fraction of a second since the insertion of the plug G.

The tertiary selection is initiated by the 45 closing of right hand contact of relay c8, completing a circuit from ground through right hand contact, wire c25, contact of relay e19 and winding of relay e1 to battery. The intermediate trunk involved is trunk 50 number 11, and the operation of determining which tens and units relays of the idle keyset shall be energized to select and connect this intermediate trunk corresponds to that of the tertiary selection, and will be 55 understood without detailed description. The keyset shown in Fig. 10 is assumed to be idle and is the first keyset of the entire group for the system. The energization of the number 1 units relay (e8) of the tertiary 60 control completes a circuit leading from ground through its left hand contact, wire e28, right hand contact of relay f16, Fig. 9, lower wiper of switch D2, number 1 bank contact on which its wiper is resting, wire 65 f36, right hand contact of relay f8, wire

f29, right hand forward contact of relay g6, Fig. 10, (this relay being normally energized with the keyset not out of service), left hand contact of relay g11, lower contact of relay g5, wire f30, and to battery 70 through the winding of relay f5. The switch g64 in circuit with the winding of relay g6 is closed to make the keyset available for service, and opened to cut the keyset out of service in case of trouble. The energization 75 of relay f5 energizes relays f1 and f2, connecting the talking conductors e35—e34 of the intermediate trunk with the talking conductors f35 and f34 of the keyset. Wire f31 of the keyset is also connected to wire e24 of 80 the intermediate trunk completing a circuit leading from battery through the winding of relay g11, wire f31, wire e24, winding of relay e19, and to ground through wire c25 and the right hand contact of relay c8. The 85 energization of relay e19 interrupts the circuit of relay e1 restoring to normal the previously energized tertiary controlling relays of Fig. 8 in the manner already described for the relays of Fig. 7. Relay g11 in operating releases relay f5 and extends the circuit of wire f29 through its forward contact, the left hand contact of relay g6, and wire g33 to the next idle keyset, as will be explained in complete detail in considering 90 Fig. 16. The energization of relay g11, by the operation of its middle contact lever, closes the locking circuit for relays f1 and f2 through non-inductive resistances g21 and g22 to ground through the upper contact of g5. The right hand contact of g11 closes a circuit from battery through the winding of relay g10, the right hand contact of g11, the lower normally closed contact of relay g3, the lower normally closed 100 contact of relay g9, and to ground through the normally closed middle contact of relay g5. The ensuing operation of relay g10 closes a circuit from ground through its left hand contact lever, the call lamp g23, wire 110 f38, and winding of relay f8 to battery. Lamp g23 is illuminated by current in this circuit constituting the calling signal before the keyset operator. Relay f8 is also energized operating the counter-magnet f3 by 115 the circuit closed at its left hand contact; and by the operation of its right hand contact lever extends the wire f36 through the normally closed upper contact of relay f9 to the circuits of the keysets on the next operator's desk, as illustrated in detail in Fig. 16. The common relay f9 is a sluggish relay energized at the initial operation of relay f5 by circuit closed through the lower contact of f5, and maintains its energization, and the circuit of wire f36 open until after the dropping back of the previously energized relay e8. The circuit closed at the right hand contact of relay g10 causes 120 the illumination of the guard lamp g24. 130

The lighting of the call and guard lamps g_{23} and g_{24} before the keyset operator, and the restoration of the tertiary control relays of Fig. 8, marks the completion of the 5 tertiary selecting operation. While the description of all that has taken place is necessarily long, the operation itself is completed within less than one-third of a second from the time the plug G is inserted into 10 the spring jack α_{16} .

By the operation of relays e_1 and e_2 , Fig. 6, and f_1 and f_2 , Fig. 9, a circuit has been closed as follows. From battery through the winding of relay b_7 , Fig. 2, wire b_{34} , contacts of relays e_1 and e_2 , wire e_{34} , Fig. 8, contacts of relays f_1 and f_2 , Fig. 9, wire f_{34} , middle normally closed contact of relay g_3 , Fig. 10, and to ground through the normally closed upper contact of relay g_9 . 15 20 The ensuing energization of relay b_7 interrupts the normal circuit extending to the wipers of the first selector switch, and by its upper contact lever connects relay b_1 to wire b_{35} , now extended to the keyset operator, 25 through the vertical off-normal contact b_{50} and the normally closed upper contact of relay b_8 . Another circuit is closed from ground through the middle contact lever of relay b_7 , through the winding of relay b_8 30 to battery. Relay b_8 in operating closes for itself a locking circuit extending through its middle contact lever to earth at the normally closed contact of off-normal springs b_{25} . Relay b_8 also closes at its lower contact a branch in shunt of the right hand contact of relay b_6 , thereby maintaining the earth connection for the relays b_5 and e_8 (regardless of the subsequent removal of the plug G) until after the interruption of the 35 earth connection at b_{25} by the first step of the first selector and until the relay b_4 is released. Therefore, after a call has once been established to the keyset it cannot be released by the "A" operator until after the 40 keyset operator has operated the first selector by means of the start button g_{26} , which starts the operation of the keyset switches.

Referring now to Fig. 10, relay g_{10} being 45 energized and the lamps g_{23} and g_{24} illuminated, the keyset operator answers the call by momentarily pressing the answering button g_{25} . This operation connects ground to the left hand contact of g_{25} , momentarily 50 energizing magnet g_{22} and operating the release lever g_{99} , restoring any previously locked keys in strips g_{42} , g_{43} and g_{44} . At the same time, the application of ground to the center contact of key g_{25} completes 55 the circuit of relay g_3 through the now closed middle contact of relay g_{10} . Relay g_3 in operating closes for itself a locking circuit extending from its winding through its lower contact lever, the normally closed 60 lower contact of relay g_9 , and to ground

through the normally closed middle contact of relay g_5 . The operation of the lower contact lever of relay g_3 also interrupts the previously established circuit through the winding of relay g_{10} , allowing this relay to 70 release after the interval determined by its sluggish characteristic. The ground connection previously traced through the lower contact of relay g_9 also serves to maintain the illumination of guard lamp g_{35} initially 75 lighted by the actuation of key g_{25} . Lamps g_{23} and g_{24} are extinguished by the release of relay g_{10} . The actuation of the upper and middle contact levers of relay g_3 interrupts at the middle contact the energizing 80 circuit of relay b_7 and connects the keyset operator's telephone set g_{36} directly with the talking wires f_{34} and f_{35} now extending to the talking strands of the cord circuit with which the calling subscriber has been 85 answered. Bearing in mind that the "A" operator has not yet restored her listening key, she hears the response of the keyset operator and repeats to the keyset operator the call number South 3456 previously assumed as that of the desired line. The calling subscriber hears this number repeated, following which the "A" operator restores her listening key and proceeds with her work of answering other calling lines. 90

The keyset operator now proceeds to set up the number South 3456 on her key-board, depressing the No. 2 key in row g_{41} (second from the bottom) as representing the South exchange, and keys number 3, 4, 5 and 6 in 100 rows g_{42} , g_{43} , g_{44} and g_{45} , respectively. The operator now actuates the start button g_{26} momentarily closing ground at each of the three contacts of this key. The closing of the center contact completes a circuit extending from ground through the winding of relay g_9 to wire f_{34} , wire e_{34} , wire b_{34} , and winding of relay b_7 to battery, thereby 105 again energizing relay b_7 and initially energizing relay g_9 . Relay b_7 in operating opens the circuit extending to condensers b_{41} and b_{42} , and reestablishes the ground connection for holding relays b_8 and b_5 energized after the breaking of ground at 110 springs b_{25} on the first step of the first selector. The operation of relay b_7 also connects relay b_1 in circuit with wire b_{35} extending to the keyset. The energization of relay g_9 deenergizes relay g_3 and again 115 lights the guard lamp g_{24} , which lamp thereafter remains lighted during the building up of the connection to the called subscriber. The operation of the lower contact lever of relay g_9 maintains the circuit of relay g_3 interrupted, and by engaging its forward 120 contact completes a locking circuit for relay g_9 extending to ground through the normally closed middle contact of relay g_5 . The actuation of the upper contact lever of relay g_9 closes a circuit extending from 125 130

ground through this contact lever, the right hand normally closed contact of relay $g12$, the center wiper $g48$ of switch D4, the bank contact at $g48$ upon which this wiper normally rests, the normally closed left hand contact of relay $g2$, and the winding of driving magnet $g20$ of switch D4 to battery. The attraction of the armature of magnet $g20$ brings the driving pawl into engagement with the next tooth of the driving ratchet of the switch and closes also the circuit of relay $g2$. The energization of relay $g2$ interrupts at its contact the circuit of magnet $g20$ releasing the magnet armature, and by retraction of the armature driving the switch wipers forward one step. This step brings each of the wipers $g47$, $g48$ and $g49$ into engagement with the first contact from the normal point in the respective sets of bank contacts. A circuit is thereby established from ground through the winding of relay $g12$, the wiper $g47$, the bank contact upon which it is now resting, the wire $f35$, wire $e35$ and wire $b35$, through the winding of relay $b1$ to battery. Relays $b1$ and $b12$ are operated by current flowing through this circuit, and serve to step the first selector switch of Fig. 2 and the switch D5 of Fig. 10, each in a rotary direction. The relay $b1$ closes the circuit of the rotary driving magnet $b20$, driving the first selector switch one step forward on the attraction of the rotary magnet armature, and at the same time closing the circuit of interrupting relay $b3$ to momentarily interrupt at the upper contact of relay $b3$ the circuit of relays $b1$ and $g12$. The relay $g12$ on energization closes the circuit of the driving magnet $g21$ of switch D5, causing the driving pawl of this switch to engage the next adjacent tooth of the driving ratchet, and the subsequent deenergization of relay $g12$, resulting from the interruption of circuit at the contact of relay $b3$ causes the release of the driving magnet $g21$, driving the switch D5 one step forward by the retraction of the switch magnet armature. The rotary stepping of the first selector switch therefore determines the rate of stepping of the switch D5, and it is merely necessary that the switch D5 shall be able to keep up with the stepping of the first selector switch in order to secure perfect unison of operation.

The first selector switch and the switch D5 continue to step in unison until the wiper $g50$ of the switch D5 makes contact with a bank contact leading to the depressed key in the row $g41$. When this occurs, a circuit is closed from ground through the wiper $g50$, the bank contact, the closed contacts of the depressed key (in this case No. 2 key in row $g41$) the contact and wiper $g48$ now in engagement, the right hand contact lever and forward contact of relay $g12$, and to battery through the winding of magnet

$g20$. The energization of magnet $g20$ over this circuit causes the switch D4 to take one step forward on the succeeding deenergization of relay $g12$. This forward step interrupts the circuit of relays $b1$ and $g12$ at 70 wiper $g47$, thereby stopping the first selector switch after it has taken the desired number of rotary steps. This forward step of switch D4 also closes a restoring circuit for switch D5 which may be traced from ground 75 through the upper contact lever of relay $g9$, the normally closed right hand contact of relay $g12$, the wiper $g48$, the bank contact upon which this wiper now rests, the wiper $g51$ of switch D5, the bank contact upon 80 which this wiper rests, the normally closed right hand contact of relay $g1$, and the winding of magnet $g21$ to battery. This energizing circuit for the magnet includes the contact of the interrupting relay $g1$, 85 and therefore, the closing of the circuit of $g1$ by the attracted armature of magnet $g21$ results in the continued stepping of switch D5 until the circuit is interrupted by wiper $g51$ reaching the normal resting point of the 90 switch. As wiper $g50$ in restoring engages the last contact before reaching normal, it closes circuit from ground through the wiper and bank contact to the winding of the relay $g16$ and battery. Relay $g16$ is a sluggish relay, and in operating closes, at its left hand contact, a circuit to energize driving magnet $g20$ of switch D4. Upon the deenergization of relay $g16$, the switch D4 therefore takes another step forward, shifting the wipers $g47$, $g48$ and $g49$ to the third contact point from normal. This completes the operation of the keyset switches D4 and D5 so far as the operation of the first selector is concerned. 105

Referring now to Fig. 2, relay $b1$ at its first energization closes circuit from ground through its lower contact lever to the winding of sluggish relay $b9$ and battery. Relay $b9$ thereafter remains energized during the 110 rotary stepping of the first selector and releases its armature at a definite time interval after the final interruption of the circuit of relay $b1$ by the shifting of wiper $g47$. The release of relay $b9$ closes a circuit which may 115 be traced from battery through the winding of relay $b2$, the vertical off-normal contact $b51$, the contact of relay $b9$, the lower normally closed contact of relay $b12$, and to ground through the now closed left hand contact of springs $b25$. The resulting energization of relay $b2$ closes at its lower contact the circuit of relay $b4$, which, in operating, opens the circuit of the switch wipers $b52$ and $b53$. Relay $b2$ also closes at 120 its upper contact the circuit of vertical driving magnet $b21$, which, by the attraction of its armature, controls the circuit of interrupting relay $b3$, causing the switch to take 125 one or more vertical steps. The circuit closed 130

at the middle contact lever of relay b_2 leads to private wiper b_{54} of the first selector and is in bridge of the branch extending through vertical off-normal springs b_{51} . The switch therefore continues to step in a vertical direction in the well-known manner until the wipers b_{54} encounter a pair of bank contacts b_{59} not connected to ground. When this occurs, the interruption 10 at the middle contact of relay b_3 , following the forward step of the vertical magnet, allows the relay b_2 to become deenergized, breaking the locking-circuit at the middle contact of relay b_2 and opening the circuit of the vertical magnet b_{21} , bringing the switch to rest. If the trunk be idle with 15 which the bank contacts b_{59} are associated, these contacts are then characterized by the absence of a ground connection. If the 20 trunk be already occupied, these contacts are then connected to ground through the wipers b_{54} of a switch which has previously selected the trunk and the circuit extending to the left hand contact of the springs b_{25} of such switch. An additional ground connection for the contacts b_{59} is also provided at the left hand contact of relay b_{18} of such 25 trunk in case the trunk has been previously selected, or in case the second selector switch 30 to which said trunk extends be in an off-normal position, the relay b_{18} being deenergized under such conditions. By the operation of the first selector switch just described, the switch wipers b_{52} and b_{53} and, 35 therefore, the wires b_{34} and b_{35} have been extended into engagement with contacts leading through talking wires b_{57} and b_{58} to the circuits of an inter-office selector functioning as a second selector and located at the 40 South exchange. The circuits of the keyset apparatus are also now in condition for the operation of this inter-office selector illustrated in Fig. 3. It should be also pointed out that under the assumption of the first 45 selector finding an idle trunk leading to an inter-office selector of the desired exchange prior to the completion of the restoration of keyset switch D_5 and the shift of switch D_4 to the third contact point from normal, 50 then no further operation of the selector switches will occur until the wipers of switch D_4 are shifted as described.

Assuming now that the wipers b_{52} and b_{53} are resting on the bank contacts leading 55 to the idle inter-office selector switch of Fig. 3, and that the wipers of switch D_4 are resting on the third contact point from normal, a circuit then exists similar to that previously traced for relay g_{12} but extending 60 now from wire b_{35} through the normally closed upper contact of relay b_4 , wiper b_{52} , talking conductor b_{57} , vertical off-normal contact h_{51} , Fig. 3, left hand contact of relay h_3 , and winding of relay h_1 to ground. 65 The previously existing circuit through re-

lay b_1 was broken at vertical off-normal contact b_{50} on the first vertical step of the first selector switch. Relays h_1 and g_{12} now operate in this circuit in a manner similar to that previously described for relays b_1 and g_{12} . When the wiper g_{50} reaches the third contact point from normal, a circuit from ground through the wiper and the No. 3 key previously depressed in row g_{42} , energizes driving magnet g_{20} as before causing a forward step of switch D_4 and again interrupting the circuit extending from relay g_{12} through the conductor f_{35} . The secondary operation of the inter-office selector of Fig. 3 corresponds with the secondary operation 75 of the first selector switch and will be understood without further description. The restoration of switch D_5 and the next forward step of switch D_4 occurs in the same manner as following the operation of the first 80 selector switch. As a result of these operations, the connection has now been extended through the wipers h_{52} and h_{53} of the inter-office selector to the wires h_{57} and h_{58} leading to the circuits of a local selector at the 85 South exchange functioning as a third selector in the system. This local selector is shown in Fig. 4.

Before proceeding with the description of 90 operation of the third selector or local selector illustrated in Fig. 4, attention should be directed to the operation of those relays of the inter-office selector of Fig. 3 which have to do with the release and guarding of the inter-office selector trunk at the time of disconnection. Referring to Figs. 2 and 3, the first energization of relay h_1 energizes relay h_5 , which thereafter maintains the attraction of its armature during the rotary stepping 95 of the inter-office selector. At the first rotary step of the switch, the left hand contact of rotary off-normal springs h_{25} is closed, completing the circuit of relay h_8 through non-inductive resistance b_9 and the forward contact of relay h_5 . The resulting energization of relay h_8 establishes for itself a locking circuit extending from battery through the winding of relay h_8 , its contact now closed, conductor b_{58} , wiper b_{53} , and winding of impedance coil b_{14} to ground. 100 This locking circuit thereafter remains intact and the relay h_8 energized until interrupted at wiper b_{53} or at the lower contact of relay b_4 at the time of release. It is also to be pointed out that the selectable 105 condition of the trunk to the inter-office selector is characterized by the presence of a normally closed circuit extending from battery through the winding of relay b_{18} , the normally closed contact of relay b_{19} , the conductor b_{58} , and the normally closed contact of off-normal springs h_{25} . When the 110 idle inter-office trunk is picked by a first selector, the relay b_{17} , Fig. 2, is instantly energized by the dropping back of relay b_3 , 115

closing at the lower contact of $b17$ a circuit to ground for continuing the energization of $b18$; while the circuit closed at the upper contact of $b17$ energizes relay $b19$, disconnecting relay $b18$ from the talking conductor $b58$. At the time of release of the first selector switch, the energization of relay $b12$ and the restoration of wiper $b54$ interrupts the circuit of relay $b17$ thereby releasing relays $b18$ and $b19$, thereby grounding the contact $b59$ through the retracted armature lever of $b18$, holding the inter-office trunk busy and unselectable until the subsequent energization of relay $b18$ through the restoration 10 of the inter-office selector to normal, closes the right hand contact of off-normal springs $b25$. The switch indicated at $b58$, Fig. 3, is provided for the purpose of interrupting the circuit to relay $b18$, preventing the selection 15 of the trunk to the inter-office selector in case it be desired to put the inter-office selector temporarily out of service for inspection or repairs.

Returning now to the operation of the 25 third selector of Fig. 4, the shift of the wiper $g47$, Fig. 10, to the fifth contact from normal, and the selection of the idle third selector by the second selector of Fig. 3, has established a circuit extending from battery through the repeating relay $j1$ of Fig. 4 to earth through the repeating relay $g12$ of Fig. 10. These two relays now operate to step their respective switches in the manner previously described with respect to relays $b1$ and $g12$. When four steps of the selector switch have been made, the circuit closed from ground at wiper $g50$ through the actuated No. 4 key in row $g43$, causes the switch $D4$ to take a forward step in the 30 manner previously described, stopping the further rotary motion of the third selector switch. This operation has caused the third selector switch to select that row of contacts corresponding to the fourth hundred of the 35 thousand (third thousand) with which the third selector is associated. The dropping back of sluggish relay $j5$ now causes the third selector to step vertically and select the contacts leading to an idle connector 40 switch in a manner which will be clearly understood in view of the drawings and previous descriptions. At the same time, the switch $D5$ is automatically restored to normal, as previously described, causing the 45 switch $D4$ to take another forward step and come to rest on the seventh bank contact from normal. The operation of the third selector, or local selector, of Fig. 4 differs 50 from that of the first selector of Fig. 2 in that the initial energization of sluggish relay $j5$ and the initial rotary step of the switch completes a circuit for relay $j8$ which, on energization, establishes for itself a locking circuit extending from its left hand contact lever through wire $h59$, wiper $h54$, right hand contact of relay $h3$, and to ground through the right hand contact of relay $h6$. It is by the subsequent interruption of this locking circuit that the local selector of Fig. 4 is restored.

The selection of the idle connector switch shown in Fig. 5 and the stepping of wiper $g47$, Fig. 10, to the seventh contact from normal, completes a circuit now extending from battery through the winding of relay $j1$, the normally closed upper contact of relay $j2$, and the upper talking conductor to earth through the winding of relay $g12$. These relays $j1$ and $g12$ now cause the rotary stepping of the connector switch and 70 switch $D5$ in the same manner as described with respect to the rotary stepping of the first selector switch. The contacts at $j25$ are closed on the first rotary step of the connector, and the first energization of relay $j1$ 75 energizes sluggish relay $j9$ completing a circuit extending from ground through the now closed upper contact lever of relay $j9$, the vertical off-normal contact $j51$ and the winding of relay $j3$ to battery. The relay $j3$ in operating completes for itself a locking circuit extending from its winding through the upper contact lever, the middle contact of relay $j5$, the right hand normally closed contact of relay $j8$, the wire $h59$, 80 wiper $h54$, and to ground through the right hand contact of relay $j3$. The actuation of the lower armature lever of relay $j3$ closes a circuit extending from ground through the contacts of springs $j25$, the lower contact 85 lever and forward contact of relay $j3$, the normally closed lower contact of relay $j4$ and winding of relay $j11$ to battery. The energization of relay $j11$ interrupts the normal circuit of the wipers $j52$ and $j53$, and 90 this interruption is maintained during the rotary and vertical stepping of the connector switch by the continued energization of relays $j3$ and $j11$. At the fifth step of the connector switch, the circuit closed from 95 ground through the wiper $g50$ and the contact leading to the actuated key No. 5 in row $g44$, causes the switch $D4$ to advance one step, as previously described, interrupting the circuit of relay $j1$ while the switch $D5$ 100 restores to normal as before. The time relation of the sluggish relay $g16$ is such that the switch $D4$, at the restoration of switch $D5$, will not advance its wiper $g47$ another 105 step to the fifth contact point from normal until a sufficient lapse of time for the necessary intervening operation of the connector switch to have occurred.

At the interruption of relay $j1$ by wiper $g47$, the sluggish relay $j9$ releases, closing 110 at its upper normally closed contact a circuit leading from battery through the winding of relay $j6$, the normally closed upper contact of relay $j9$, the contact springs $j51$, 115 the actuated upper contact lever of relay $j3$, 120 the right hand contact of relay $h3$, and to ground through the right hand contact of relay $h6$. The circuit 125

- the middle contact of relay j_5 , the right hand normally closed contact of relay j_8 , and to ground through wire j_59 , wiper j_54 , and the right hand contact of relay j_3 . The 5 ensuing operation of sluggish relay j_6 completes, by its middle contact, a locking circuit effective upon the subsequent energization of relay j_9 ; substitutes the vertical magnet j_{21} for the rotary magnet j_{20} by 10 the operation of its upper contact lever; and at its lower contact lever closes the circuit of sluggish relay j_{12} , energizing relay j_{12} in preparation for the busy test of the desired line.
- 15 Wiper g_{47} , when stepped to the ninth contact point from normal, again closes the circuit of relays j_{12} and j_1 , and these relays again cause the step-by-step motion of their respective switches. In this case, the connector switch is stepped in a vertical direction by the operation of vertical magnet j_{21} and interrupter relay j_2 . Upon the seventh 20 step of the switch a circuit is closed from ground through wiper g_{50} and the previously depressed No. 6 key in row g_{45} , again completing the circuit for advancing wiper g_{47} one step as before. The breaking of the circuit of relay j_1 by wiper g_{47} brings the wipers of the connector switch to rest 25 30 on the contacts of the line having the call number South 3456.

The explanation of the connector switch being given seven steps in the vertical direction to reach the contact of line South 3456 and of the arrangement of the contacts in row g_{45} whereby the actuation of the No. 6 key closes the circuit of the seventh contact from normal, is as follows. It is desirable, under certain circumstances, that connectors 35 be provided which, instead of being directly driven to each contact in its vertical rows of bank contacts, may instead be stepped to the first contact of a vertical row or to the first contact of a sub-group 40 45 of contacts in a vertical row, and be thereafter automatically controlled to automatically select the first idle set of contacts in the group to which it has been directly driven. Connectors operating in this manner are sometimes referred to as P. B. X. 50 55 connectors. In the use of this arrangement, particularly in applying it to previously existing exchange systems, it has been found desirable to use a call number for the group 60 65 to which the connector is directly driven having the numeral "0" for its units digit. The first line of the group to which the connector is driven is therefore a line which, under the methods heretofore employed, would be reached on the tenth step of the switch, and would therefore necessarily be the last contact of a group rather than a contact at the beginning of a group. In order, therefore, to use the numeral "0" as the 65 units digit of such group call numbers, I ar-

range the last row of the operator's keyset as indicated in Fig. 10, connecting that contact point of switch D_5 leading to the No. 1 key of rows g_{41} , g_{42} , g_{43} and g_{44} to the No. 10 key in the units row g_{45} . The contact connected with the No. 2 key in the first four rows is connected with the No. 1 key in the units row, and so on. At the connector switch, the wiring of the subscribers' lines to the multiple bank contacts in the vertical rows is arranged in a corresponding manner;—that is, the lines having call numbers using "0" as the units digit are wired to the bottom set of contacts in each row; the lines having call numbers using the numeral "1" as the units digit are wired to the second set of bank contacts from the bottom in vertical rows, and so on. By arranging the connections in the manner described, I am able, by means of any keyset in the system, to control P. B. X. connectors in a manner allowing the employment of group call numbers having "0" as the units digit.

Following the selection of line South 3456 by the connector switch, the switch D_5 restores to normal as previously described, causing the switch D_4 to advance one step as the wiper g_{50} energizes and releases relay j_{16} . This step brings the wiper g_{48} into engagement with the 11th contact point 95 from normal, closing a circuit leading from battery through the winding of relay g_5 , the eleventh contact point and wiper at g_{48} , the normally closed right hand contact of relay g_{12} to ground through the contact 100 and upper contact lever now actuated of relay g_9 . The relay g_5 becoming energized interrupts at its upper contact lever the locking circuit of relay f_1 and f_2 extending through resistances g_{22} and g_{21} , disconnecting the key-set from the intermediate trunk. The actuation of the middle contact lever of relay g_5 closes an energizing circuit for magnet g_{20} extending through the contact of relay g_2 , causing 105 switch D_4 to advance one step to normal. At the same time, the actuation of the middle contact lever of relay g_5 interrupts the previously existing locking circuit extending from ground through the middle contact lever and normally closed contact of relay g_5 , the lower contact lever and winding of relay g_9 , wires f_{34} , e_{34} and b_{34} , and to battery through the winding of relay b_7 , Fig. 2. The advance of wiper g_{48} from the 110 eleventh contact point to the normal point has caused the release of relay g_9 , while the interruption of circuit through winding of relay g_9 has restored this relay and relay b_7 . The apparatus associated with the key-set is now in its normal position ready for use in the establishment of another connection. The results following the de-energization of relays f_1 , f_2 and b_7 will be described 115 later. Assuming that the line South 3456 be 120 125 130

not already engaged, the interruption of circuit through relay j_1 , when wiper j_{47} is advanced to the tenth contact point, results in the following operation. The release of relay j_1 is followed by the release of relay j_9 , and the ensuing release of relay j_6 releases relay j_{12} . The release of relay j_{12} closes a circuit extending from battery through the winding of relay j_4 , the normally closed contact of relay j_{12} , the now closed vertical off-normal contact j_{50} , wire j_{59} , wiper j_{54} to ground through right hand contact of relay j_3 . The ensuing operation of relay j_4 interrupts at its lower normally closed contact the previously existing energizing circuit of relay j_{11} , and closes at the forward contact of its lower armature lever an energizing circuit for ringing switch magnet j_{16} . The actuation of the upper contact lever of j_4 disconnects relay j_1 from the talking conductor j_{57} and completes the circuit of this talking conductor through to the condenser j_{43} . By the release of relay j_{11} the circuit of the wipers j_{52} and j_{53} is now completed. Assuming the circuits of the line South 3456 to be as indicated at C, Fig. 1, a circuit is closed extending from battery through the winding of impedance coil j_{14} , the wiper j_{52} , wire j_{57} , and left hand winding of cut-off relay a_4 to ground. Relay a_4 is thereby energized interrupting the circuit of the called line normally extending through the line relay a_3 .

The energizing circuit closed for ringing switch magnet j_{16} is an automatically interrupted circuit extending from battery through the winding of relay j_{18} , the contact of relay j_{17} , winding of magnet j_{16} , lower contact lever and forward contact of relay j_4 , lower contact lever and forward contact of relay j_3 , and to ground through the off-normal springs j_{25} . Current in this circuit first energizes relay j_{18} connecting battery at its left hand contact directly to the winding of relay j_{16} ; and at its right hand contact closing the circuit of relay j_{17} , which operation interrupts the circuit initially closed through relay j_{18} . Relays j_{18} and j_{17} are sluggish relays and in operating cause the driving magnet j_{16} to attract its armature following the energization of relay j_{18} ; and to retract its armature advancing the ringing switch one step at the retraction of relay j_{18} , following the interruption of its circuit by the energization of relay j_{17} . The ratchet j_{99} has fifteen teeth and advances the spring actuating cams in the following sequence during each cycle of its rotary operation: At the first step cam springs j_{31} and j_{32} break and j_{37} makes. At the second step j_{33} , j_{34} and j_{36} make contact. At the third, fourth and fifth steps no change is made in the contacts, this period constituting the ringing period of the cycle. At the sixth step, contacts j_{33} and

j_{36} are broken, and at the seventh step contact j_{35} closes. At the eighth step contacts j_{34} and j_{35} break, contacts j_{31} and j_{32} make; and no further change takes place as the result of the ninth, tenth, eleventh, twelfth, thirteenth and fourteenth steps. At the fifteenth step j_{37} breaks, completing one cycle of operation, and the cycle is repeated indefinitely due to the continued vibration of relays j_{17} and j_{18} until such a time as the called subscriber responds, or the calling subscriber gets tired of waiting and hangs up. When springs j_{31} and j_{32} break the circuit extending back toward the calling subscriber is interrupted and the closing of springs j_{33} and j_{34} at the next step connects the ringing generator j_{41} in circuit through lamp j_{45} , contact j_{33} , wiper j_{53} , wire j_{58} to the sub-station line, returning through wire j_{57} , wiper j_{52} , cam springs j_{34} and non-inductive resistance j_{42} to the return side of the generator through the circuits of the central battery. The calling generator remains connected during the third, fourth and fifth steps of the ringing switch. The making of contact j_{37} at the first step provides that the ringing switch shall complete its cycle of operation following the response of the called subscriber; and the closing of contact springs j_{36} at the second step completes a tone circuit to the condenser j_{44} advising the calling subscriber that the connection has been completed and ringing current applied to the desired line. This tone circuit includes the generator j_{41} , lamp j_{48} , induction coil primary j_{40} , the secondary side of this induction coil being connected through condenser j_{46} to the contact springs j_{36} of a plurality of ringing switches. At the sixth step the breaking of contact at springs j_{33} and j_{36} disconnects the tone circuit from the calling line and disconnects the ringing generator from the called line. At the seventh step the closing of contact at springs j_{34} momentarily short circuits the two limbs of the called line through the closed contacts j_{34} and j_{35} , thus discharging the line to prevent a false operation of relay j_{10} when the talking conductors are closed at the eighth step by the making of contacts j_{31} and j_{32} .

Following the eighth step of the ringing switch, the previous or subsequent response of the called subscriber is effective to energize the relay j_{10} by current flowing through this relay, the line limbs, the sub-station telephone, and the left hand winding of relay a_4 , Fig. 1. The energization of relay j_{10} closes at its lower contact the circuit of sluggish relay j_5 . The operation of relay j_5 interrupts at its middle contact the previously established locking circuit for relay j_3 , and the ensuing release of relay j_3 opens at its lower contact lever the circuit previously closed at the eighth step by the closing of contacts j_{31} and j_{32} .

ously established through magnet $j16$ causing the operation of this magnet to terminate at the completion of its cycle when contact $j37$ is broken at the fifteenth step. The 5 actuation of the lower contact lever of relay $j5$ prevents the reestablishment of an energizing circuit for relay $j11$ upon the release of relay $j3$; and by the operation of its upper contact lever completes a circuit extending 10 from ground through the winding of impedance coil $j15$ to wire $i57$, and thence through wire $h57$, wire $b57$, the upper normally closed contact of relay $b7$, the contact of relay $b16$, and the winding of relay $b11$ 15 to battery. The closing of this circuit through impedance $j15$ provided supervision for the "A" operator as follows. The energization of relay $b11$ closes circuit from ground through the winding of impedance 20 coil $b15$, left hand contact of relay $b11$, wire $b24$, thimble of jack $a16$, sleeve strand of plug G , and winding of relay $a7$ to battery, energizing relay $a7$ and extinguishing supervisory lamp $a13$. The energization of relay 25 $b11$ also completes a circuit extending from battery through winding of relay $b13$, right hand forward contact of $b11$, left hand forward contact of $b6$ to ground. Relay $b13$ becoming energized completes for itself a 30 locking circuit extending from its winding through its left hand contact to the circuit previously traced. The release of relay $b11$ subsequent to the completion of this locking circuit causes the restoration of the first selector in a manner hereinafter described. 35

Referring back now to the deenergization of relays $f1$ and $f2$, Fig. 9, following the momentary energization of relay $g5$ and the release thereby of relay $b7$, it is now to be 40 pointed out that the first selector switch now being off-normal, the release of relay $b7$ had interrupted at its middle contact the previously existing circuit of relay $b8$. The release of relay $b8$ releases relay $b16$, which in 45 its turn connects relay $b11$ to the upper talking conductor of the first selector circuit. The retraction of the middle contact lever of relay $b7$ has likewise interrupted the circuit previously existing extending through the 50 winding of relay $b5$, wire $b31$, and the winding of relay $c8$. The resulting release of relay $b5$ completes the circuit of the lower talking conductor at the upper normally closed contact of relay $b5$; and the retraction 55 of the left hand contact lever of relay $c8$ interrupts the locking circuit of relays $c1$ and $c2$, including resistances $c21-c22$, allowing the restoration of these relays and therefore the disconnection of the intermediate 60 trunk from the first selector switch. The intermediate trunk is therefore now free to be used in extending another calling line to a keyset operator, while the circuits of the first selector and the succeeding switches 65 used in building up a connection are in con-

dition for conversation. Battery for the energization of the transmitter of the calling subscriber is furnished through the relay $a6$ and left hand winding of relay $a2$, Fig. 1, and battery for the energization of the transmitter of the called subscriber is furnished through the winding of relay $j10$, Fig. 5, and the left hand winding of relay $a4$, Fig. 1.

It may here be pointed out that if the 75 called subscriber were located within the same exchange as the calling subscriber, then the first selector instead of picking a trunk leading to an inter-office selector, might instead pick a trunk leading to a local selector 80 as illustrated in Fig. 4, which, in turn, would select a trunk leading to another local selector of similar arrangement, the first mentioned local selector functioning as a second selector, and that last mentioned functioning, 85 as a third selector. The operation of the apparatus under this assumption will be obvious from the previous description. Similarly, if the switch functioning as a second selector is to be located at an exchange different from those exchanges at which are located the first selector and the connector, then the inter-office selector of Fig. 3 functioning as a second selector would select a trunk leading to a switch of similar character at the terminating exchange functioning as a third selector, which, in its turn, would select an idle connector. Under this assumption, the relay $h8$, Fig. 3, of the inter-office selector functioning as a third selector 90 would be locked up in multiple with the corresponding relay of the inter-office selector functioning as a second selector. The operation of the various switches under this last assumption will be understood from the 95 drawings and previous description.

At the conclusion of conversation, the replacement of the receiver at the calling station illuminates a supervisory lamp $a12$, Fig. 1, in the well-known manner. The replacement of the receiver at the called station deenergizes the relay $j10$ thereby releasing also the sluggish relay $j5$. This relay is made sluggish in order that the connection may not be accidentally released through an unintended operation of the switch hook at the called sub-station. The release of relay $j5$ disconnects the impedance coil $j15$ from talking conductor $i57$ thereby 110 releasing relay $b11$ at the first selector. The release of relay $b11$ disconnects the impedance coil $b15$ from talking conductor $b24$, thereby interrupting the circuit of relay $a7$, illuminating lamp $a13$ and completing the 115 disconnect signal before the "A" operator, who may now take down the connection on observation of this condition. The release of relay $b11$ also completes a circuit leading from battery through the winding of sluggish relay $b12$, the normally closed middle 120

in addition add before beginning of line 1,252,974 of the number of lines at 060 wiper 17
 100 and 101 and 102 and 103 and 104 and 105 and 106 and 107 and 108 and 109 and 10
 contact of relay b_4 , the right hand contact 100 now closed of relay b_{13} , the right hand normally closed contact of b_{11} , and to ground 105 through the left hand forward contact of relay b_6 . Relay b_{12} in operating closes at its middle contact an energizing circuit for relay b_4 , thereby interrupting the circuit previously existing extending from impedance coil b_{14} to battery through the winding of relay b_8 , disconnecting wipers b_{52} and b_{53} . The actuation of the middle contact lever of relay b_4 closes at its forward contact an energizing circuit for release magnet b_{22} completed through the lower contact now closed 15 of relay b_{12} . The energization of the release magnet restores the first selector switch wipers and shaft to normal in the well-known manner, restoring also the off-normal springs b_{25} , b_{50} and b_{51} . By the restoration 20 of springs b_{25} , the locking circuit previously established for relay b_{12} at its lower contact lever is interrupted and the relay released at the end of the restoring motion of the switch. Prior to the removal of the plug 25 G from jack a_{16} , the relays b_6 and b_{13} are held energized, and the relay b_{13} , by the interruption at its middle contact, maintains interrupted the circuit extending through wire b_{29} to relay d_1 , Fig. 7, thereby preventing 30 a false operation of relay d_1 at this time. Relays b_6 and b_{13} are released by the removal of plug G, leaving the first selector in condition for use in establishing a subsequent connection.

35 By the release of relay b_8 following the restoration of the first selector switch, a circuit is closed extending from battery through the winding of sluggish relay b_6 , the right hand contact of relay b_8 , the right 40 hand contact of relay b_5 to earth at the left hand contact of springs b_{25} . The ensuing energization of relay b_6 completes for itself a locking circuit at its left hand contact lever in shunt of the contact of relay b_8 ; 45 and by the actuation of its right hand contact lever closes the circuit of relay b_4 . The circuit of the release magnet b_{22} is thereby closed at the middle contact of relay b_4 , through the left hand contact of spring b_{25} , 50 restoring the switch mechanism in the well-known manner. As previously pointed out, the contacts of the two-wire trunk leading to the inter-office selector of Fig. 3 are guarded during the restoration of this 55 switch, or in case it should fail to restore, by the release of relay b_{18} , during this period. I have shown in association with release magnet b_{22} , a pilot relay b_{10} provided with contacts for closing the circuit 60 of a signal lamp. The relay b_{10} is common to a plurality of switches and will thus give a signal in case any of the switches with which it is associated fail to completely restore to normal following the restoration of 65 relay b_8 . It is to be understood that a relay

1,252,974 of the number of lines at 060 wiper 17
 100 and 101 and 102 and 103 and 104 and 105 and 106 and 107 and 108 and 109 and 10
 contact of relay b_4 , the right hand contact 100 now closed of relay b_{13} , the right hand normally closed contact of b_{11} , and to ground 105 through the left hand forward contact of relay b_6 . Relay b_{12} in operating closes at its middle contact an energizing circuit for relay b_4 , thereby interrupting the circuit previously existing extending from impedance coil b_{14} to battery through the winding of relay b_8 , disconnecting wipers b_{52} and b_{53} . The actuation of the middle contact lever of relay b_4 closes at its forward contact an energizing circuit for release magnet b_{22} completed through the lower contact now closed 15 of relay b_{12} . The energization of the release magnet restores the first selector switch wipers and shaft to normal in the well-known manner, restoring also the off-normal springs b_{25} , b_{50} and b_{51} . By the restoration 20 of springs b_{25} , the locking circuit previously established for relay b_{12} at its lower contact lever is interrupted and the relay released at the end of the restoring motion of the switch. Prior to the removal of the plug 25 G from jack a_{16} , the relays b_6 and b_{13} are held energized, and the relay b_{13} , by the interruption at its middle contact, maintains interrupted the circuit extending through wire b_{29} to relay d_1 , Fig. 7, thereby preventing 30 a false operation of relay d_1 at this time. Relays b_6 and b_{13} are released by the removal of plug G, leaving the first selector in condition for use in establishing a subsequent connection.

35 By the release of relay b_8 following the restoration of the first selector switch, a circuit is closed extending from battery through the winding of sluggish relay b_6 , the right hand contact of relay b_8 , the right 40 hand contact of relay b_5 to earth at the left hand contact of springs b_{25} . The ensuing energization of relay b_6 completes for itself a locking circuit at its left hand contact lever in shunt of the contact of relay b_8 ; 45 and by the actuation of its right hand contact lever closes the circuit of relay b_4 . The circuit of the release magnet b_{22} is thereby closed at the middle contact of relay b_4 , through the left hand contact of spring b_{25} , 50 restoring the switch mechanism in the well-known manner. As previously pointed out, the contacts of the two-wire trunk leading to the inter-office selector of Fig. 3 are guarded during the restoration of this 55 switch, or in case it should fail to restore, by the release of relay b_{18} , during this period. I have shown in association with release magnet b_{22} , a pilot relay b_{10} provided with contacts for closing the circuit 60 of a signal lamp. The relay b_{10} is common to a plurality of switches and will thus give a signal in case any of the switches with which it is associated fail to completely restore to normal following the restoration of 65 relay b_8 . It is to be understood that a relay

similar to b_{10} is provided in association with the release magnet of each of the several types of two-motion switches here described. At the final restoring motion of the inter-office selector the locking circuit of relay b_6 is interrupted at the left hand contact of springs b_{25} , restoring this relay, and the closing of the right hand contact at b_{25} completes the circuit of relay b_{18} , thus placing the circuits of the inter-office selector in their normal selectable condition.

By the restoration of the inter-office selector of Fig. 3, the circuit previously existing and holding energized relay j_8 , Fig. 4, is interrupted at wiper j_4 . The resulting 80 release of relay j_8 closes the circuit of relay j_4 at its normally closed center contact, and the resulting energization of relay j_4 completes at its middle contact the energization of release magnet j_{22} , restoring the local 85 selector of Fig. 4 to normal in the well-known manner. It is to be pointed out that following the release of relay j_8 , a ground connection is maintained on wire j_{59} preventing the selection of the local selector 90 while restoring, or in case it fails to restore. The switch indicated directly below j_{59} is intended to render the local selector 95 unselectable in case it is desired to cut it out of service for inspection or repairs.

It will be evident from the above that in 100 case the called subscriber has responded to his call signal, he then thereafter controls the release of the first selector, second selector and third selector switch mechanisms. Under this condition he also controls the release of the connector, but independently of the selector switches. Going back to the 105 release of relay j_5 following the replacement of the receiver at the called station, the circuit closed at the lower contact of relay j_5 energizes relay j_{11} . The energization of relay j_{11} interrupts the circuits of the wipers j_{52} — j_{53} and completes a circuit extending from battery through the winding of release magnet j_{22} , the middle contact of 110 relay j_{11} , the normally closed upper contact of relay j_3 , the middle contact of relay j_5 , the lower normally closed contact of relay j_3 , and to earth through the closed contacts 115 of springs j_{25} . The energization of magnet j_{22} restores the switch shaft and wipers to normal, restoring therefore off-normal contacts j_{50} and j_{51} , while the circuit connection extending from the middle contact 120 of relay j_5 through the normally closed right hand contact of relay j_3 to wire j_{38} guards the trunk leading to the connector switch from selection until the springs j_{25} are restored at the final restoring motion of 125 the switch. The restoration of springs j_{25} to their normal position releases relay j_4 , relay j_{11} and switch magnet j_{22} , thereby leaving the connector circuits in their normal selectable condition. The lever switch shown di- 130

rectly below $i59$ is used to ground the bank contact to which this wire leads, thereby preventing the selection of the connector in case this be desired.

- 5 Considering now the release under the assumption that the called subscriber does not answer the ringing of the sub-station bell, the calling subscriber on hanging up would give the customary disconnect signal to the 10 "A" operator, who would thereupon remove the plugs P and G. Bearing in mind that under this condition the relay $b13$ has not been locked up, it will be seen that the release of relay $b6$ follows the removal of the 15 plug G closing at its center contact a circuit leading from battery through the winding of relay $b12$, the normally closed middle contact of relay $b4$, the middle contact of relay $b6$, to earth through the left hand contact of 20 springs $b25$. The energization of relay $b12$ under this condition closes the locking circuit of relay $b12$, and at its middle contact closes an energizing circuit for relay $b4$. The energization of relay $b4$ completes the 25 energizing circuit of release magnet $b22$, and the release of the switch mechanism thereafter proceeds in the manner previously described. This results in the release of inter-office selector, Fig. 3, and local selector, 30 Fig. 4, as previously explained, but the connector is released in a different manner. Bearing in mind the called subscriber has not responded, relay $j3$ has therefore not been released. This relay, as well as relay 35 $j4$, are at this time held up by the energizing circuit completed through their windings and through wire $i59$, wiper $i54$, to earth at the right hand contact of relay $j3$. This holding circuit is interrupted by the restoration 40 of wiper $i54$, releasing both relays and completing the circuit of relay $j11$ through the normally closed lower contact of relay $j5$ and the middle contact of relay $j3$ to earth at the springs $j25$. The attraction of relay 45 $j11$ now completes the energizing circuit of release magnet $j22$ at its middle contact, as previously described, thus effecting the release of the connector under this condition.
- If, for any reason, it should be desired to 50 release a partially built up connection as, for example, in case a mistake has been made in giving a call number, this may be instantly accomplished by the withdrawal of the plug G. The release of the first selector, second 55 selector, third selector and connector switches, under this condition, is accomplished in the same manner as in case the subscriber fails to respond, restoring whichever ones of these switches have been 60 stepped off-normal by the deenergization of their respective relays $j8$, $j8$ and $j3$. The release of the intermediate trunk and restorator of the engaged keyset apparatus under this condition is accomplished as follows. Bearing in mind that relay $b7$ is be-

ing held energized under this condition of release, it will be seen that by the dropping back of relay $b6$ on the removal of plug G, a circuit for energizing relay $b12$ is completed from ground at left hand contact of springs 70 $b25$ through middle contact of relay $b6$, and to the winding of relay $b12$ through the normally closed middle contact of relay $b4$ as soon as this relay $b4$ has been released. The operation of relay $b12$ interrupts at its 75 upper contact the circuit extending through the winding of relay $b5$ and by wire $b31$ to the winding of relay $c8$, Fig. 6. The resulting release of relay $c8$ removes at its right hand contact the ground connection from 80 wire $c25$, thereby releasing $g11$ at the keyset. The release of relay $c8$ releases relays $c1$ and $c2$ thereby disconnecting the intermediate trunk from the first selector switch and releasing relay $b7$. The restoration of 85 relay $g11$ releases relays $f1$ and $f2$, thereby disconnecting the keyset from the intermediate trunk. The interruption of the previously existing circuit through wire $f34$ releases relay $g9$, establishing a restoring 90 circuit for the switch D4, which may be traced from ground through the normally closed middle contact of relay $g9$, the wiper $g49$, the bank contact upon which this wiper is resting, and to battery through the winding of relay $g5$. The resulting energization of relay $g5$ closes at its middle contact the stepping circuit of magnet $g20$, thus restoring the switch D4 to normal. On reaching 95 the normal point, the wiper $g49$ completes 100 a circuit leading from ground through normally closed middle contact of relay $g9$, wiper and normal contact at $g49$, wiper $g51$, and the contact upon which it is resting, to battery through the interrupter contacts of 105 relay $g1$ and the winding of driving magnet $g21$. This interrupter circuit is maintained driving the switch D5 until the normal resting point is reached. All of the involved apparatus is thus restored to normal in case 110 the plug G be removed during the process of building up a connection to the called line.

Assuming now that the called line South 115 3456 were found to be already engaged, the operation of the connector switch is as follows. Under this condition, the bank contact engaged by wiper $j52$ will have been connected to the active terminal of the central battery either through the winding of 120 impedance $j14$ of another connector switch, or through the winding of relay $a5$ of an answering cord. At the time the wipers $j52$ and $j53$ came to rest on the selected bank contact, the relay $j6$ was being held energized by relay $j9$, and the latter relay being held energized by the intermittent operation of relay $j1$. Upon the interruption of circuit through relay $j1$, the ensuing release of relay $j9$ completes a circuit leading from 125 130

ground, Fig. 4, through wire 59, right hand normally closed contact of relay 58, vertical off-normal contact 50, winding of relay 57, normally closed contact of relay 59, lower contact now closed of relay 52 to wiper 52, and thence to the battery connection of this contact in case the called line be engaged, energizing relay 57. The energization of relay 57 under this condition completes an energizing circuit from wire 59 for the winding of relay 58, thereby completing a locking circuit for relay 58 at its right hand contact lever. The interruption at this time of the normally closed right hand contact of relay 58 releases relay 58, thereby establishing at its upper normally closed contact and middle contact the restoring circuits for relay 51 and magnet 52 previously described. The relay 58, however, remains locked up, and by its middle contact connects a source of characteristic busy tone current to the lower talking conductor and condenser 44. At the time relay 57 became connected to the bank contact of the called line, the relay 51 was held energized by the circuit extending through the normally closed lower contact of relay 54 and the normally open lower contact of relay 58. The line of the called subscriber was therefore not connected to and the presence of the impedance coil 54 was not allowed to interfere with the test of the called line. It will also be seen that the subsequent release of relay 52 does not result in the energization of the ringing switch magnet 56 because of the prior operation of relay 58 under the busy condition. Following the restoration of the connector switch under this condition, the relay 58 remains energized holding the busy tone circuit connected to the talking conductor until released by the interruption of its energizing circuit at wiper 54. The release of the first selector, second selector and third selector switches under this condition is accomplished by the removal of the plug G following the disconnect signal by the calling subscriber in the manner described in case of no answer by the called subscriber.

Referring to Fig. 4, I have illustrated at 50 and adjoining 52, a source of busy tone current extending by wire 56 to the top or eleventh bank contact engaged by wiper 53 of the local selector switch in case all ten trunks in a selected row are found to be engaged at the time the switch is operated. The make contact engaged by wiper 52 at the eleventh step is indicated as connected by wire 55 with a relay 56. It is to be understood that the wires 55 and 56 are connected to the corresponding contacts in each vertical row of the switch. A similar arrangement is provided for the other selector switches of the system being indicated by the relay 56 in Fig. 2, and by the relay 46 in Fig. 3. The purpose of the relay is to pro-

vide means for restoring the keyset apparatus immediately to normal releasing its connection with the first selector, in case all trunks of a selected group be found to be busy. The purpose of the busy tone arrangement is to give to the calling subscriber a characteristic signal in case of such busy condition in order that he may replace his receiver and allow the connection to be released. The busy tone arrangement consists of a series of non-inductive resistances which may be ordinary incandescent lamps indicated at 26 to 30, and included in circuit with a high speed interrupter 31, and the central battery. A second interrupter 32 of relatively slow speed is provided to break up the tone resulting from the high speed interrupter in such manner as to give a characteristic signal. The interrupter 32 is connected at an intermediate point of the series of non-inductive resistances in order that the voltage applied to the condenser 33 and wire 56 may be made sufficiently low to avoid causing inductive disturbances in the other circuits of the system. The wire 56 may be assumed to lead to the contact of relay 58, Fig. 5, as indicated. This busy tone arrangement may be made common to all of the switches of an exchange. It is believed to be a new and novel arrangement possessing the advantage of not creating the high voltage impulses resulting from the use of the prior art arrangement in which a repeating coil or transformer winding is included in circuit with the high speed interrupter, and therefore not causing the objectionable inductive disturbance found in the device of the prior art mentioned.

Referring to the operation of the keyset apparatus under the busy trunk condition, the selector switch on reaching the eleventh set of bank contacts comes to rest by the release of relay 52. The ensuing release of relay 54 completes a circuit extending from wire 56 through relay 55 and wiper 52, and thence by wires 57, 57, 58, 59 and 53 to earth through the winding of relay 52. The resulting vibration of sluggish relay 56 and the intermittent operation of relay 52 thereafter causes the keyset switches D4 and D5 to continue with their previously uncompleted cycles of operation. These switches are restored to normal and the intermediate trunk and relay 57 are released following the advance of wiper 54 to the eleventh contact point all in the manner previously described. The release of relays 55 and 57 completes the circuit of the talking conductors through to the wipers 125 of the selector switch now resting on the eleventh contact set in a vertical row, and the calling subscriber hears the characteristic tone signal indicating that all trunks in the desired group are busy. Upon the

replacement of his receiver, the operator releases the engaged switches by the removal of the plug G, as previously described. The operation in case the first selector of Fig. 2, 5 or the inter-office selector of Fig. 3, is stepped to the eleventh contact of a vertical row, is the same as with the switch of Fig. 4, and therefore need not be described in detail.

10 Referring again to Fig. 4, I have shown at $i24$ a magnet adapted when energized to operate a graphic register or counter. The circuit of this magnet is controlled at one point by the right hand contact of relay $i8$ and as indicated at $i35$ and $i36$ by the same contact of corresponding relays $i8$ of the other local selector switches of the group to which the switch of Fig. 4 belongs. By this arrangement, a circuit for magnet $i24$ is completed when all local selector switches in the group are in use and the resulting indication furnishes information as to the time and amount of traffic being handled by the switch group. It is to be understood that a similar magnet and circuit may be associated with contacts controlled by the relays $h8$ (Fig. 3) of a group of inter-office selectors. A similar arrangement may be provided for a group of first selectors by the provision of 20 suitable contacts on the relays $b6$ of such group. A similar register magnet may be associated with a group of connector switches in the same manner by the provision of serially related contacts on relays $j3$ and $j4$, as will be clearly understood from the present description.

Referring now to Figs. 9 and 10, I have here shown a switch D2 for guarding the tertiary selecting operation. In case, 40 through defective condition of any keyset, an intermediate trunk should fail to be selected and connected to a keyset, the switch D2 will then advance one more step, cutting out the three keysets of the operator's position in which the defective keyset is located. When this occurs, circuit is closed for the alarm bell $f46$ through the middle contact bank $f38$ of the switch, advising the attendant of the condition. While the trouble is being located, the switch $f40$ is thrown to the right to prevent the continued ringing of the bell, and after the trouble has been remedied the switch D2 is manually restored to its normal position, again closing the circuit of bell $f46$ to insure that the switch $f40$ shall also be restored.

The operation and control of switch D2 is as follows. When ground is applied to start wire $e28$ by the operation of a units series 60 relay as $e8$, relays $f10$ and $f5$ are simultaneously energized. The operation of relay $f5$ closes at its lower contact the circuit of relay $f9$, and at its next lowest contact the circuit extending from ground at the upper contact 65 of relay $g5$ through wire $f41$ and wire $f42$

to the winding of relay $f15$. At its third lowest contact relay $f5$ closes a circuit extending from battery through the winding of relay $g15$ and to earth through the center contact now closed of relay $f9$. The circuit 70 now closed at the contact of relay $g15$ is at this time held open at the lowest contact of relay $f9$, and the switch magnet $f20$ therefore remains deenergized. The energization of relay $f15$ through the circuit of wire $f42$ 75 interrupts at its right hand contact the circuit otherwise closed for the winding of relay $f13$ at the contact of relay $f10$, preventing the establishment of an energizing circuit for magnet $f20$ through the vibrating 80 contact of $f16$ under this condition. Relays $f9$ and $f10$, and relays $f12$, $f13$, $f14$ and $f15$ are sluggish relays, while relay $g15$ is a relay much more sluggish than those just mentioned. The time characteristic of these 85 relays is such that if the connection of the intermediate trunk to the keyset is established in the normal manner, the ground will be removed from wire $e28$ and from wire $f41$, and the various relays involved will return to normal without having caused an operation of switch magnet $f20$.

If, at the time of selection, however, the circuit of wire $e28$ be accidentally broken toward the keyset, the relay $f5$ will not be operated and the energization of relay $f10$ will close a circuit as follows. From ground through contact of relay $f10$, right hand contact of relay $f15$, left hand normally closed contact of relay $f12$, and winding of relay $f13$. The energization of relay $f13$ will connect this same ground through normally closed left hand contact of relay $f11$ to winding of relay $f12$. The energization of relay $f12$ will break the circuit of relay $f13$, and upon its retraction cause the completion of an energizing circuit for relay $f11$. Relay $f11$ will thereby establish for itself a locking circuit extending from its right hand contact to ground at the contact of relay $f10$. 100 If, therefore, relay $f5$ has remained unenergized and wire $e28$ has remained connected to ground during the time period required for the operation just described, the magnet $f20$ will be energized and subsequently deenergized by the circuit which it closes, energizing relay $f16$, and the switch thereby advanced until a contact $f39$ is reached leading to an operator's position in the serially related group of positions beyond the point of interruption. When this occurs, the resulting operation of the newly selected relay $f5$ will interrupt the stepping circuit of switch D2 at the right hand contact of relay $f15$, and the selection of the intermediate trunks will then proceed in the normal manner. As will be subsequently explained, the keysets and operators' positions are arranged in what may be termed 115 a circular series relation, and the stepping 120 125 130

of the switch D2 to a contact beyond that of the position in which the defective keyset is found, therefore results merely in cutting out of service the particular position containing the defective keyset.

In case the start wire $e28$ at the time of selection is intact, and the relay $f5$ becomes energized but fails to release as through a failure of relay $g11$ to become energized, the switch $D2$ is caused to advance as follows. The previously described circuit closed through wire $f42$ now becomes effective energizing first relay $f15$ which, in its turn, energizes relay $f14$, and relay $f14$ locks itself through the circuit of wire $f42$ interrupting the circuit of relay $f15$. Upon the dropping back of relay $f15$, the previously described circuit for the stepping operation of magnet $f20$ is completed at the right hand contact of relay $f15$, and the switch $D2$ takes one step releasing the previously energized relay $f5$ and bringing the keyset apparatus of another operator's position into circuit. If, instead of relay $f5$ being held energized as through a failure of $g11$ to energize, there should be established a vibratory condition of relays $f5$ and $g11$, as might occur through a failure of relays $f1$ or $f2$ to become locked up at the time of selection, then the switch $D2$ would be advanced as follows. Bearing in mind that relay $g15$ is more sluggish than the other sluggish relays of the guarding apparatus, this relay will be understood to remain energized during the vibration of relay $f5$ and the consequent vibration of relay $f9$. As a result of this relation, then at the time when relays $g11$ and $f9$ are retracted, a circuit is closed for energizing magnet $f20$, which may be traced from ground at the upper contact of relay $g5$ through the normally closed middle contact of relay $g11$, the contact of relay $g15$, wire $f32$, the lower contact now closed of relay $f9$ and the winding of magnet $f20$. At the subsequent energization of relay $f9$, the resulting deenergization of magnet $f20$ causes the switch $D2$ to advance one step cutting out the operator's position containing the defective apparatus. In this same connection, it should be pointed out that during periods of high traffic density at the point of tertiary selection, a considerable number of intermediate trunks will be selected each second, and the successive operations of the relays $f5$ of the corresponding keysets tend to keep the contacts of relay $f15$ constantly actuated. The controlling apparatus involving wire $f32$ and relays $f9$ and $f15$ serves to differentiate between this condition and the vibratory condition of a pair of relays $f5$ and $g11$ just described.

Referring to Fig. 7, apparatus is here shown, including the rotary switch D , for guarding against delay or failure which would otherwise result from accidental in-

terruptions or mechanical defects in the apparatus involved in the operation of the secondary selecting apparatus. Referring first to relay $d15$, it will be seen that this relay becomes energized by a circuit closed at the left hand contact of any relay $d1$, $d2$, $d11$ or $d12$ which may be actuated. Relay $d15$ controls at its contact the normally closed circuit of an extra slow relay $d16$. Under normal condition of operation, the relay $d15$ will not remain actuated for a sufficient length of time to allow the deenergization of relay $d16$; but if there be a delay in selecting the first selector trunk with which the relay $d1$ is associated, relay $d16$ will, after a predetermined interval, release its armature, closing at its left hand contact an alarm circuit indicated at N. A., and at its right hand contact a circuit for driving magnet $d20$. The energization of this magnet closes the circuit of sluggish relay $d18$, which in turn closes the circuit of sluggish relay $d17$, interrupting the circuit of magnet $d20$ and causing the switch D to advance its wipers one step. This stepping operation will be repeated at intervals as determined by the time characteristic of relays $d17$ and $d18$ until the release of relay $d15$ by the release of previously energized relays $d1$ through the selection of the first selector trunks with which these relays are associated. It will be noted also that the energization of relay $d18$ interrupts at its upper contact the battery connection of wire $d25$. This interruption is therefore effective at each step of the switch D to deenergize any previously energized relays corresponding to $d3$, $d4$, $d13$, $d5$ and $d8$. As a result of this operation, if there be at this time a plurality of relays $d1$ in an energized condition, then when the circuit of wire $d25$ is subsequently closed to battery but a single relay $d1$ will become first effective to cause a secondary selection. The particular relay $d1$ which shall become effective depends upon the preferential relation between the several relays at this time as determined by the position of the switch D and by the serial relation of the relays in the tens series group and in the units series group, respectively. Regarding the relay $d5$ as the first relay of the tens series group and the relay $d7$ as the tenth relay of the tens series group with the switch D resting in the position shown in the drawing, it will be seen that there is a circular series relation of these relays with respect to the wire leading from the right hand anvil contact of relay $d5$ to the right hand contact lever of relay $d6$, from the anvil contact of this lever through the corresponding contacts of the other relays of the series, and finally through the right hand lever and contact of relay $d5$ back to the right hand contact lever of relay $d5$. It will also be observed that a wire extends from the right hand contact lever of relay $d5$ to the right hand contact of the switch D .

each of these relays to bank contacts arranged in similar order at $d60$ of the switch D. Each of the tens series relays represents a different group of ten first selector trunks and relays $d1$, and it will therefore be apparent that if several relays $d1$ be simultaneously energized and therefore several relays of the tens series group become energized on the dropping back of relay $d18$, then but one relay in the tens series group will become effective to cause the operation of a relay $d13$, this effective relay being that energized relay of the series nearest in serial relation to the contact point at $d60$ upon which the switch wiper is then resting. A corresponding relation exists with respect to the relays of the units series group, as $d8$, and the bank contacts and wiper at $d61$. Each relay of the units series group corresponds to a particular numeral of the units digits representing the numerical relation between the first selectors in a group of one-hundred. In case of the simultaneous energization of several relays $d1$ in the same group of ten, then but one of the thereby energized relays in the units series group is effective to extend ground from the wiper at $d61$ to a contact of a relay $e5$, the effective one being likewise determined by the position of the wiper at $d61$.

As previously described the intermediate trunks are arranged in groups of ten, and the so-called circular series relation is also found with respect to the trunks in each such group. Referring to Fig. 6, it will be noted that a circuit extends from the normally open left hand contact of relay $e8$ through the contact of relay $e9$ to the left hand contact lever of relay $e10$, and from the forward contact associated with this lever through the contact of relay $e11$ and as indicated at $e50$ through the corresponding contacts of the succeeding trunks in the series to the contact lever of relay $e12$ (indicating the last trunk of the series) and from the associated forward contact through the contact of relay $e13$ back to the left hand contact lever of relay $e8$. Each left hand contact lever of the relays corresponding to $e8$ is connected to a corresponding bank contact at $d62$ of the switch D2. It will therefore be apparent that the particular intermediate trunk which is brought into service at the time of secondary selection will depend upon the position of the switch wipers at $d62$ and upon which trunks of the group are already in use and their relays $e8$ energized. It has already been pointed out that the selection of a first selector by an intermediate trunk results in the continued energization of relay $e8$; and as indicated in the drawing, the actuation of the left hand armature of relay $e8$ operates to extend the circuit of wiper $d62$ through to the relay $e5$ of that trunk next in serial relation.

It will be evident from the above description that if the energization of a relay $d1$ is not followed by the selection of the first selector with which the relay is associated, then the switch D will start advancing and continue its step-by-step motion until reaching a contact at $d62$ leading to an intermediate trunk by means of which the selection may be accomplished in case the delay is due to trouble in an intermediate trunk. It will also be evident that the order of precedence as between sub-groups of ten first selectors and as between the ten first selectors in a sub-group is shifted at each step of the switch D, and if a failure to select a first selector be due to trouble related to a particular first selector or sub-group of first selectors, the stepping of the switch will allow the selection and connection of first selectors or sub-groups of first selectors not directly involved in the defective condition. At the same time, the closing of the alarm circuit gives the necessary notification to the attendant of the presence of such defective condition.

The guarding apparatus for the tertiary selection has been described with respect to the guarding of the start wire $e28$. The guarding of the circuits involved with the tens series group and the units series group of relays shown in Fig. 8, corresponds exactly to that shown in Fig. 7. The relays $e15, e16, e17, e18$, correspond respectively to relays $d15, d16, d17$, and $d18$; and the switch D1 with its wipers and bank contacts $e60-e61$ and driving magnet $e20$, is the same as the corresponding parts of the switch D. The switch D1 has no set of bank contacts and wipers corresponding to $d62$ because of the provision of the additional switch D2 illustrated in Fig. 9. The upper contact of relay $e16$ is to be understood as controlling an alarm circuit extending to that indicated at N. A. of Fig. 7.

Referring further to Fig. 9, the magnet $f3$ energized by the actuation of relay $f8$, is to be understood as being the actuating magnet of a register or call counter. Relay $f8$ is energized whenever one of the three calling signal lamps $g23, g33, g43$, is illuminated. These three lamps together with relays $f8$ and $f9$ represent the sub-group of three keysets which are preferably assigned to each operator's position. The contemplated arrangement involves the provision of a desk or table for each operator upon which is mounted three sets of keys each connected as illustrated at $g41-g45$, together with the keys $g25, g26, g27$ and lamps $g23, g24$ and $g35$ which are provided in association with each complete set of keys. The magnet $f3$ is therefore energized each time a call lamp appears at an operator's position or desk and is released with the extinction of the call lamp, and therefore

63 serves as a means of recording the number of calls answered at the desk with which it is associated.

64 The relay f_8 , Fig. 9, serves, by its right hand contact lever, to disconnect the circuit of the start wire f_{42} from the associated desk immediately following the illumination of a call lamp, and by closing its forward contact to continue the start wire through 10 to the next desk of the series. The operator is thus prevented from receiving a second call until the extinguishment of a prior illuminated call lamp by the operation of answering key g_{25} . This condition, as well 15 as the relation between a plurality of sub-groups of keysets, is more completely illustrated in Fig. 16 of the drawings, to which reference should now be made. In this drawing, I have indicated six operators' 20 desks, each provided with three keysets, making a total of eighteen keysets. The wiper f_{21} is that wiper illustrated in Fig. 9 as associated with the bank of contacts f_{39} , and is resting on the bank contact directly 25 related to the first desk of the series. The relays f_9 , f_9 , g_5 , g_6 and g_{11} are the same as the correspondingly designated relays in Figs. 9 and 10, and are those of the first keyset of the first desk. The second and third 30 keysets of this desk are indicated by similar relays of which f_6 and f_7 correspond to f_5 , g_5 and g_6 correspond to g_5 , g_6 and g_7 correspond to g_{11} , g_6 and g_7 correspond to g_6 , and keys g_{65} and g_{74} correspond to 35 g_{64} . The relay f_9 is common to the three keysets of a desk and therefore appears but once in the circuits of the first desk thus illustrated at V. The corresponding apparatus of the second desk is indicated at 40 T, and the corresponding apparatus of the last desk is indicated at R; the relays f_{91} and f_{95} correspond to relay f_9 , and the relays f_{71} and f_{75} correspond to relay f_8 . The third, fourth, and fifth desks, with the three 45 keysets for each, are indicated by the relays f_{72} , f_{73} , f_{74} , which correspond to relay f_8 , and by relays f_{92} , f_{93} and f_{94} which correspond to relay f_9 .

50 The keys corresponding to g_{64} are to be understood as located at the chief operator's desk, or corresponding location, and serve when closed to place the associated keyset in service by the resulting energization of relay g_9 . It will be evident that the release of a key g_{64} results in disconnecting the circuit of start wire f_{47} from the associated keyset and extending it through to the next keyset in the series. It will also be evident from this diagram that the energization of a relay f_8 at the time a call signal lamp is illuminated serves to cut out the start wire from the associated desk and to extend it through to the next desk. It will also be evident from this diagram that in case all 60 three keysets of a desk be simultaneously in

use, the circuit of start wire f_{47} will be extended through to the next desk in the series by reason of the contacts closed at relays g_6 , g_{11} , g_76 and g_77 , it being understood that relays g_5 , g_5 and g_5 are inert, and that the 70 circuits of relays g_6 , g_6 and g_7 have been closed by their respective cut-in keys g_{64} , g_{65} and g_{74} . It is further apparent that in case all keysets or desks which may have been put in service at any time become simultaneously busy, the circuit of start wire f_{47} will then extend through the entire series of desks to the wiper and normal bank contact at f_{37} energizing relay f_{44} and illuminating lamp f_{45} . This lamp is located at the desk of the chief operator and its illumination constitutes a signal that all desks in service are busy and that additional desks or keysets should be put in service if any be available. It is also to be pointed out that this relay 85 f_{44} is disconnected in case the switch D_2 should be advanced as a result of delay in a tertiary selecting operation at which time the engagement of the wiper f_{37} with another contact completes a circuit of start 90 wire f_{47} extending back to the point f_{36} , thus establishing the same sort of a circular series relation between the several desks as is found between the several intermediate trunks of a sub-group. The wiper f_{21} at f_{39} 95 now being stepped ahead until the accidental break in the start wire circuit has been passed, all keysets become at once available for service except those of the desk in which the interruption is present.

100 A further guarding feature is illustrated in Fig. 10 comprising the lamp g_{18} and alarm relay g_{17} . These are placed on the wire chief's desk or other suitable location and serve to indicate any failure to complete the building up of a desired connection which might be due to the accidental interruption or grounding of the circuit extending from the keyset through wire f_{35} to the several switches used in completing a connection. The circuit of relay g_{17} and lamp g_{18} is controlled by the sluggish relays g_{13} and g_{14} following the energization of relay g_9 and the connection of their circuit to earth at the upper normally open contact of 115 relay g_9 . Upon the actuation of the start key g_{26} , the circuit closed at its right hand contact energizes relay g_{13} , and simultaneously the circuit closed at the upper contact of relay g_9 energizes relay g_{14} . It will be 120 evident that the circuit of relay g_{17} remains interrupted if relays g_{13} and g_{14} be both energized or both inert. Bearing in mind that the driving magnet g_{21} of switch D_5 continues its intermittent operation from the 125 time the start key is actuated until the building up of the connection is completed and relay g_9 released, it will be seen that relay g_{17} is thereby continuously vibrated during this period. This vibration serves, by means of 130

the left hand contact lever of relay g_1 , to keep relays g_{13} and g_{14} both continuously energized during such period of operation. If, however, an accidental ground connection should appear on wire f_{35} , magnet g_{21} would obviously remain energized, allowing relay g_{14} to drop back and complete, through its normally closed contact and normally open contact of relay g_{13} , the circuit 10 extending through the alarm relay g_{17} . If the circuit of wire f_{35} should be interrupted accidentally at a time when the wiper at g_{50} is being stepped in search of a contact leading to a depressed key, then magnet g_{21} and 15 relay g_1 would remain inert holding up relay g_{14} and completing the circuit of relay g_{17} through the normally closed contact of relay g_{13} . Inasmuch as relay g_9 is released by the operation of relay g_5 as wiper g_{48} engages the eleventh contact point from normal upon the final movement of wiper g_{50} to its normal contact, the circuit which would otherwise cause the operation of relay g_{17} is 20 interrupted at the upper contact lever of relay g_9 and no alarm results from the stopping of magnet g_{21} at this time.

Referring further to the keyset apparatus shown in Fig. 10, provision is made for restoring the keyset after the completion of 25 connections involving only the operation of the first selector switch as, for example, in case the calling subscriber desires to be switched to a toll board or to an information desk, or other special trunk. In this 30 case, the key g_{27} is utilized, and this key may be in the form of an additional contact associated with certain keys in row g_{41} , or may be actuated at the time of actuating the start key g_{26} , or in any other suitable 35 manner. It will be seen that with start keys g_{26} and g_{27} simultaneously closed, a circuit is completed for relay g_4 , which in turn by its left hand contact lever completes an energizing circuit for relay g_9 and 40 a locking circuit for itself, and relay g_9 extending to ground through the middle normally closed contact of relay g_5 . The operation of the middle contact of relay g_4 connects ground to wiper g_{49} , and the interruption of the right hand contact of relay g_4 disconnects the first two contacts engaged by wiper g_{49} as the switch is advanced during the operation of the first 45 selector switch. Upon the advance of wiper g_{49} to the third contact point from normal following the operation of the first selector, a circuit is then completed from ground through the middle contact of relay g_4 , wiper g_{49} , bank contact upon which the 50 wiper is resting, and winding of relay g_5 to battery. The resulting energization of relay g_5 now establishes the regular releasing condition heretofore described, and switches D4 and D5, with the other keyset

apparatus, returns to its normal condition 55 ready for another connection.

It has been previously pointed out that the system of the present application provides means for utilizing call numbers of fewer digits than the maximum number of 70 digits possible of use in the system. This is accomplished by means of the release magnet g_{22} and contacts g_{96} , g_{97} and g_{98} shown in Fig. 10. The contacts g_{96} , g_{97} and g_{98} are associated, respectively, with 75 the rows of keys indicated at g_{44} , g_{43} and g_{42} . They are so arranged that by means of the locking mechanism, or otherwise, the contact will be closed at all times when there is no key locked in the actuated position in the corresponding row. Therefore, the operator by actuating her listening key contacts at g_{25} energizes release magnet g_{22} operating release bar g_{99} . This operation releases any previously locked keys in rows 80 g_{42} , g_{43} and g_{44} , at the same time closing the contacts g_{96} , g_{97} and g_{98} . The closing of these contacts is of the same effect as if the tenth key in each of the three rows 85 mentioned had been actuated. The operator 90 thereafter sets up the desired number on the key-board, as previously described, actuating only those keys corresponding to the call number as given her. As an example, if the call number South 6 were given, she 95 would actuate the No. 2 key in the left hand row (corresponding to South exchange) and the No. 6 key in the right hand row, disregarding entirely the keys in the second, third and fourth rows. It 100 will be apparent from the foregoing description of operation of the selector switches that following the operation of the start key g_{26} , the associated first selector will be stepped to its second row of bank 105 contacts, selecting a second selector which will step to its tenth row of bank contacts, selecting a third selector which will be stepped to its tenth row of bank contacts and selecting a connector which in its turn 110 will be stepped to the tenth row of bank contacts, and thereafter stepped vertically to the contact of line No. 6 corresponding to the actuated units key. Obviously, in a system like that of the present application, 115 it will be always desirable to operate a key in the right hand row of the key-board corresponding to the exchange in which the desired subscriber is located. In a single office system, however, this would be unnecessary, 120 and the left hand row of keys could therefore be arranged in the same manner as the second, third and fourth rows of Fig. 10, thereby making it possible to utilize all of 125 those call numbers represented by numbers having fewer digits than the highest call number in the system. For example, in a system with a capacity for numbers up to

9999, it is possible, by means of my invention, to utilize as call numbers those numbers running from 1 to 999, and thus avoid changing previously assigned call numbers 5 in an already existing exchange of the manual type. This, I believe, has not been possible prior to the invention of the present application.

Referring now to the modification of Fig. 10 19, I have illustrated in Figs. 11, 12 and 13, in connection with Figs. 3 to 10, inclusive, a system in which the primary selection is performed automatically rather than by means of an "A" operator's cord pair. In 15 this system the first selectors of Fig. 13 are arranged similarly to those indicated in Fig. 2 except that instead of terminating in a spring jack a_{16} , they each terminate in a group of tens and units relays as indicated 20 in Fig. 11. A corresponding modification in the method of releasing the first selector is also present. For the purpose of this description, it may be assumed that the subscribers' lines are arranged in sub-groups 25 of one-hundred, and that the first selectors are arranged in groups of ten, there being a group of ten first selectors associated with each group of one-hundred lines. Each subscriber's line, as indicated in Fig. 11, is provided with a cut-off relay r_{23} , and a line relay r_{21} , and a plurality of such lines is indicated by the additional line and cut-off relays $r_{22}-r_{23}$, $r_{31}-r_{33}$, $r_{32}-r_{34}$, respectively. The wires r_{57} and r_{58} are to be 30 understood as extending to the bank contacts of connector switches like those of Fig. 5, and these wires may also extend to manual multiple spring jacks, if desired. The arrangement of the line relays, control relays 0 and tens and units relays of Figs. 11 and 12 corresponds exactly to the arrangement of the similar relays in Figs. 6 and 7, the line relay r_{21} having its counterpart in the relay d_1 of Fig. 7. The relay r_8 in its control, of 5 start wire s_{26} corresponds to relay c_8 , and the relay r_9 is momentarily energized by the operation of r_5 to interrupt the start wire and prevent energizing a relay r_5 of a first selector subsequent in serial relation in the 10 group of first selectors, just as relay c_9 is energized by the operation of relay c_5 for the same purpose in the control circuits of Fig. 6. The relation of a group of first 15 selectors of Fig. 13 to a group of one-hundred subscribers' lines corresponds exactly with the relation of a group of ten intermediate trunks to a group of one-hundred first selectors, and the arrangement and operation of the controlling relays and circuits for the primary selection is exactly the same as that of the corresponding relays involved in the secondary selection previously described except as hereinafter may be pointed out. It will therefore be unnecessary to

here trace the several circuits and operations of the primary selection in detail. 65

With the understanding that the line of subscriber A' is line No. 11 in its group, the raising of the sub-station receiver energizes relay r_{21} , thereby energizing relays 70 s_5 , s_3 , s_{13} , s_8 and s_4 applying ground to the left hand and third contact points of relay r_5 . Relay r_5 is likewise energized over start wire s_{26} , causing the energization of tens relay r_1 and units relay r_2 . A circuit 75 is thereby closed through cut-off relay r_{23} in circuit with relay r_8 causing the release of relay r_{21} and the restoration of the controlling relays of Fig. 12. The energization of relay r_8 shifts the start wire s_{26} to 80 the next idle first selector in the group and completes at its right hand contact a locking circuit through wire r_{29} and the normally closed middle contact of relay t_{12} to 85 maintain the energization of relays r_1 and r_2 . The relay t_{26} being now energized by current flowing through the sub-station A' in turn energizes relay t_{15} to maintain at 90 its upper contact an additional earth connection for the locking wire r_{29} and thus prevents the release of relays r_1 and r_2 until the subscriber at A' replaces his receiver at the conclusion of conversation. The relay r_8 by the operation of its middle contact has closed the circuit of relay t_6 95 which, by its right hand contact, closes a circuit leading from ground through right hand contact of rotary off-normal springs t_{25} , right hand contact of t_6 , right hand contact of relay t_{18} , upper contact of relay t_6 100 t_{12} , and thence by wire b_{29} to relay d_1 on Fig. 7. The energization of relay d_1 starts the secondary selecting operation, and the process of reaching the keyset operator and the completion of the connection to the desired subscriber thereafter proceeds as described in connection with Fig. 18. 105

Following the first step of the first selector switch, the calling subscriber may release all of the apparatus involved by the replacement of his receiver as follows. The replacement of the receiver interrupts the circuit of relay t_{26} , which thereby releases sluggish relay t_{15} , and this relay closes at its lower contact a circuit extending from ground through left hand contact of springs t_{25} , lower contact of relay t_{15} , middle normally closed contact of relay t_4 (as soon as this relay releases in the operation of the first selector) and winding of relay t_{12} to 110 battery. Relay t_{12} thereby closes at its lower contact a locking circuit to the contact at t_{25} , and at its middle contact breaks the locking circuit of relays r_1-r_2 , closing the energizing circuit of relay t_4 . Relay t_4 then 120 completes at its middle contact the energizing circuit of release magnet t_{22} restoring 125 the first selector switch and the succeeding

selectors and connector which may have been operated in the same manner as described for Fig. 18. The energization of relay t_{12} will similarly, by the interruption of its upper contact, release the intermediate trunk and keyset. When the called subscriber responds, the application of impedance coil j_{15} (Fig. 5) to talking conductor i_{57} energizes relay t_{11} , Fig. 13. The operation of relay t_{11} now completes a circuit extending from ground through left hand contact of relay t_6 , normally open contact of relay t_{11} , and winding of relay t_{13} to battery, causing relay t_{13} to lock itself to the ground at relay t_6 . At the conclusion of conversation, if the calling subscriber be the first to replace his receiver, the release of relay t_{15} will complete the energization circuit for relay t_{12} , and cause the release of all switches except the connector switch, as heretofore explained; the release of the connector switch being at this time prevented through the energization of relay t_{10} maintained by current flowing through the sub-station of the called subscriber. In case the called subscriber be the first to replace his receiver, the release of relay t_{10} releases relay j_5 in turn disconnecting impedance j_{15} and releasing relay t_{11} . Relay t_{11} upon dropping back closes at its right hand contact an energizing circuit for relay t_{12} extending from ground at t_6 through now closed right hand contact of relay t_{13} , the normally closed contact of relay t_4 , and energizing relay t_{12} , causing the release of the first selector, second selector and third selector switches. The connector switch is independently released at this time as previously described. Under this condition, the subsequent restoration of the receiver at sub-station A' causes the release of relay t_{15} , breaking the locking circuit of relays r_1 and r_2 , thereby restoring relays r_8 and r_{28} and leaving all apparatus in condition for another call.

It is to be pointed out that when relay t_7 is initially energized, the closing of its middle contact causes relay t_8 to become energized and locked to ground through the right hand contact at t_{25} . By this means, relay t_{11} is held disconnected from the upper talking conductor of the first selector and wire b_{35} during conversation between the operator and the calling subscriber. The lower contact of t_8 closed at this time provides an alternative path to ground to that closed through contact of relay t_6 for the winding of relay t_5 . The relay b_8 of Fig. 2 performs similar functions in the first selector of that figure.

It will be observed from the above description that in the system of Fig. 19, the first selector, second selector, and third selector are all released by that subscriber who first replaces his receiver at the conclu-

sion of conversation, and that this release is secured by control exercised over a portion of the talking circuit of the connection. This is a feature which I believe to be of importance and not heretofore accomplished.

Referring to the modifications indicated in Figs. 14 and 15, I have here shown means whereby calls originating at any particular point or group of points in the system may be differentiated from other calls. As here shown, these differentiations may be utilized in various ways, one being to allow a call originating in a sub-exchange to be completed without requiring the use of talking trunks extending to the main exchange in the conversation between the subscribers thus connected. Referring first to Fig. 17, I have indicated at N-3300 and N-2400 sub-exchanges tributary to the main exchange N. These sub-exchanges are to be understood as provided with first selectors, second selector, third selector and connector trunks, and with primary selecting apparatus of the character indicated by Fig. 19, and with intermediate trunks extending directly to the tertiary selecting point L and keyset operators' Q at the central exchange M. With the understanding that the trunks leading to the second or inter-office selectors at the N main exchange appear in the third row of all first selector switches in the system, and that in setting up a call number beginning with N or North, the keyset operator always actuates the No. 3 key in the first row, it will be apparent that a call for a subscriber whose call number is North 2456 would necessarily be extended, first, to a second selector at the North exchange when originated at any point except sub-exchange N-2400. The second selector at the N exchange would then be operated to pick a third selector corresponding to the second thousand of the N exchange but located at the exchange N-2400, which selector in its turn would pick a connector in the sub-group corresponding to the fourth hundred of the second thousand. Similarly, a call originating at the sub-exchange N-2400 and terminating at the sub-exchange N-3300, or at any North number not located at sub-exchange N-2400, would necessarily be trunked first to a second selector at the North exchange. Because of these conditions, it will be apparent that a call originating at sub-exchange N-2400 and intended for subscriber North 2456 would necessarily be trunked to the N main exchange and then back over another trunk to the same sub-exchange N-2400 in the absence of special means to take care of this condition.

By means of the modification illustrated in Figs. 14 and 15, I provide for the condi-

tion last described in the following manner. Fig. 14 indicates a portion of the tens and units tertiary selecting relays of the keyset apparatus illustrated in Figs. 9 and 10; and 5 Fig. 15 shows a portion of the keyset apparatus of Fig. 10. Relays f_1 , f_2 and f_3 are the same as similarly designated relays in Fig. 9 except for the added contact points hereinafter described, and relays f_{31} , f_{32} , 10 f_{41} and f_{42} are additional tens and units relays of the same keyset. Relays g_{11} , g_{12} , g_1 and g_2 , and traveling switches D_4 and D_5 of Fig. 15 are the same as the correspondingly designated parts in Fig. 10. I 15 have also shown in Fig. 15 at g_{41} , g_{42} and g_{43} the first six keys in the correspondingly numbered rows of Fig. 10, but provided with an added set of contacts for each key. The tens and units keys of rows g_{44} , 20 g_{45} , Fig. 10, as well as the other apparatus there shown, are to be understood as present in the arrangement of Fig. 15, although not actually illustrated. It is to be further understood that those intermediate trunks 25 serving sub-exchange N-2400 terminate in the left hand contacts of relay f_{41} , Fig. 14. Assuming now that a call originates at sub-exchange N-2400 and that the desired line is located in the same sub-exchange, the call 30 number being North 2456, the line of the calling subscriber will be extended through to the keyset of Fig. 15 (located at Q, Fig. 17) by energizing relay f_{41} , and that one of the relays f_2 , f_{32} or f_{42} corresponding to 35 the units number of the intermediate trunk employed. The energization of relay f_{41} connects at its second lowest contact an earth connection to wire x_{39} which extends through to the fourth key, x_4 of the hundreds row g_{43} . The call number North 2456 is represented on the operator's key- 40 board by the No. 3 key in the left hand row for the exchange named "North," by the second key x_2 in row g_{42} for the thousands digit, by the fourth key x_4 in the hundreds row for the hundreds digit, and by the fifth and sixth keys in the tens and units rows g_{44} and g_{45} . The keyset operator upon receiving this call number therefore actuates 45 the corresponding keys. By reason of my invention, the call having originated at the sub-exchange N-2400, the No. 3 key in the first row instead of being effective to cause the associated first selector to be stepped to 50 the third row, closes a circuit in connection with the actuated keys x_2 and x_4 which may be traced from battery through the winding of relay x_{11} , the right hand contact of key No. 3 first row, the right hand contact of key 55 x_2 , and the right hand contact of key x_4 through wire x_{39} to ground at the contact of relay f_{41} . The relay x_{11} is thereby energized and by the operation of its contact shifts the wire x_{31} from its normal connec- 60

tion with the first bank contact at g_{50} and 65 into connection with the sixth bank contact at g_{50} . The effect of this is the same as if the No. 6 key in the first row had been actuated instead of the No. 3 key. The operation is the result of the combined action of 70 the tens relay f_{41} corresponding to the group of intermediate trunks leading from the sub-exchange N-2400 with the actuation of those keys corresponding to the call numbers of the sub-exchange N-2400 from 75 which the intermediate trunks lead. The first selectors at sub-exchange N-2400, as at other similar sub-exchanges, are to be assumed as being provided with second selectors appearing on the sixth row of bank 80 contacts of their respective first selectors, and these second selectors lead to third selectors also located within the respective sub-exchange connecting with the customary groups of connector switches. It will now 85 be apparent that as a result of the energization of relay x_{11} , the first selector switch now associated with the subscriber who desires to be connected with North 2456, instead of being stepped to the third row and 90 selecting a trunk leading to the N main exchange, will be stepped to the sixth row and pick a second selector located within the sub-exchange, and thereafter the connection will be completed thus wholly within 95 the sub-exchange in which the call originates.

It will be apparent that the method of completing connections within sub-exchanges may be applied to any number of sub-ex- 100 changes in a multi-office system, and that the invention is not limited to sub-exchanges or to the particular method or means here disclosed.

In connection with Figs. 14 and 15, I have 105 illustrated at x_{13} a relay operated whenever an intermediate trunk of that group corresponding to relay f_{31} is selected, this relay controlling contacts for the energization of a register magnet x_{14} and for a signal or alarm lamp x_{15} , and for a wire x_{40} corresponding to wire x_{39} leading to the key x_3 of the hundreds row g_{43} . By this modification it is possible to secure a similar operation to that described involving wire x_{39} , 110 or to relate the intermediate trunks connected at relay f_{31} with first selectors located at a particular exchange or intended for a particular class of service, and thus secure a signal or a graphic record whenever a call 115 is originated by a subscriber served by the first selectors in question. As an example, these first selectors might be first selectors at a private branch exchange requiring a particular manipulation of the operator's 120 keys which would be indicated by the lamp x_{15} , or might be first selectors of subscribers furnished only with measured serv- 125

ice and thus similarly indicated to the operator; or the first selectors might represent a group of subscribers or a group of trunks for which the volume of traffic was to be investigated, in which case a graphic record or a registration of this traffic would be secured by means of the magnet $\alpha 14$. A further modification of this feature is illustrated by means of the wire $\alpha 36$ and relay magnet $\alpha 16$ brought into circuit whenever a relay $f2$ is energized. With this arrangement, an indication or record, or other desired operation, would be effected whenever an intermediate trunk was connected having a units digit numeral corresponding to the relay $f2$. A further modification is illustrated by means of relay magnet $\alpha 17$ and wire $\alpha 37$ extending through the lower contact of relay $f42$ and to earth through the second lowest contact of relay $f1$. By this modification, the previously described results would be secured in case of a calling subscriber being connected with a keyset operator by means of a predetermined one of the intermediate trunks of the entire group. In the particular instance illustrated, this would be trunk No. 13 of the group, assuming the tens and units relays to be arranged as in Fig. 11 or Fig. 6 of the drawings, and this trunk might be a single intermediate trunk serving a private branch exchange, or one of a particular few intermediate trunks designated for use only by subscribers not allowed toll connections or by pay-station lines or for other special requirements. The scope of the improvement illustrated by means of Figs. 14 and 15 will be apparent without the presentation of further examples of its utility, and I do not wish to be limited to the means or results here disclosed.

I claim:

1. A telephone call distributing system comprising a plurality of subscribers' lines, a group of call receiving units divided into sub-groups, a plurality of trunk lines divided into groups, and means for extending the line of a calling subscriber by means of any trunk of any group to any call receiving unit in any sub-group.

2. A telephone call distributing system, comprising a plurality of call receiving units divided into associated sub-groups, a call signal for each unit, means for causing the display of said call signals, and means effective during the display of the call signal of any one unit for temporarily disassociating the sub-group containing said one unit from the other sub-groups of said plurality.

3. In an automatic telephone exchange system, a group of trunk lines, a traveling switch adapted to automatically select a non-busy trunk of said group, manually controlled means actuated to initiate the selec-

tive operation of said switch, and means for automatically restoring said manually controlled means in case all trunks of said group are busy.

4. An automatic telephone system comprising subscribers' lines, a plurality of traveling switches for building up a connection extending between a calling and a called line, a manually actuated device for directly controlling the operation of said switches, controlling circuits extended from said device to each of said switches, and means associated with said device for automatically indicating the presence of an accidental interruption in said controlling circuits.

5. An automatic telephone system comprising subscribers' lines, a plurality of traveling switches for building up a connection extending between a calling and a called line, a manually actuated device for directly controlling the operation of said switches, controlling circuits extended from said device to each of said switches, and means associated with said device for automatically indicating the presence of an accidental shunt of said controlling circuits.

6. An automatic telephone system comprising subscribers' lines, a plurality of traveling switches for building up a connection extending between a calling and a called line, a manually actuated device for directly controlling the operation of said switches, controlling circuits extended from said device to each of said switches, and means associated with said device for automatically indicating the presence of an accidental shunt or interruption of said controlling circuits.

7. An automatic telephone system comprising subscribers' lines, a plurality of sequentially operated switches for building up a connection extending between a calling and a called line, a manually actuated device for directly controlling the operation of said switches, controlling circuits extended from said device to each of said switches, and means associated with said device for automatically indicating the presence of an abnormal interruption to the sequential operation of said switches.

8. An automatic telephone system comprising subscribers' lines, a plurality of traveling switches for building up a connection extending between a calling and a called line, an automatically restored device for directly controlling the operation of said switches, controlling circuits extended from said device to each of said switches, and indicating means associated with said device effective in case of failure of restoration of said device.

9. In a telephone call distributing system a group of circuits, a circuit selecting mecha-

means for selecting lines to be connected, a connector switch, a source of calling current, a calling switch individual to said connector comprising contact members automatically intermittently actuated on selection of an idle line to interrupt normal circuits of said connector switch and to connect the terminals of the selected line to said source, and additional contact members for said calling switch actuated following the disconnection of said source to discharge the line conductors of the selected line.

10. In a telephone call distributing system, a group of circuits, a circuit selecting mechanism associated therewith, other related similar circuit selecting mechanisms, a circuit for initiating operation of said mechanism, means effective in case of failure of selection to substitute one of said other mechanisms for the first mentioned mechanism, and an alarm circuit established by the actuation of said means.

10. In a telephone call distributing system, a group of circuits, a circuit selecting mechanism associated therewith, other related similar circuit selecting mechanisms, a circuit for initiating operation of said mechanism, means effective in case of failure of selection to substitute one of said other mechanisms for the first mentioned mechanism, an alarm circuit closed on actuation of said means, a switch for interrupting said alarm circuit, and an alternative alarm circuit including a normally open contact of said switch completed on restoration of said means.

11. In a telephone exchange system a source of characteristic tone comprising a source of direct current an interrupting device and non-inductive resistance in circuit therewith, and means automatically actuated for connecting the line of a calling subscriber in circuit with an intermediate point of said resistance.

12. In an automatic telephone system, the combination of a connector switch provided with a pair of traveling terminals, constituting extensions of talking conductors, a pair of contact pieces for each of said terminals adapted on actuation to interrupt the normal circuit of said terminals, a pair of contact pieces for each of said terminals adapted on actuation to connect a source of calling current to said terminals, driving mechanism for sequentially actuating said pairs of contact pieces, and means, effective responsive to the idle condition of a line selected by said connector, for actuating said driving mechanism.

13. In an automatic telephone system, the combination of a connector switch provided with a pair of traveling terminals constituting extensions of talking conductors, a pair of contact pieces for each of said terminals adapted on actuation to interrupt the normal circuit of said terminals, a pair of contact pieces for each of said terminals adapted on actuation to connect a source of calling current to said terminals, a pair of contact pieces adapted on actuation to short-circuit said terminals, driving mechanism for sequentially actuating said pairs of contact pieces, and means, effective responsive to the idle condition of a line selected by said connector, for actuating said driving mechanism.

14. In an automatic telephone system the combination of a connector switch, a source

of calling current, a calling switch individual to said connector comprising contact members automatically intermittently actuated on selection of an idle line to interrupt normal circuits of said connector switch and to connect the terminals of the selected line to said source, and additional contact members for said calling switch actuated following the disconnection of said source to discharge the line conductors of the selected line.

15. In an automatic telephone system, the combination of a connector switch, a source of calling current, a calling switch individual to said connector comprising contact members automatically intermittently actuated on selection of an idle line to interrupt normal circuits of said connector switch and to connect the terminals of the selected line to said source, and additional contacts for said calling switch intermittently actuated to connect a source of characteristic tone to the talking circuit extending toward the calling subscriber.

16. A telephone exchange system comprising a primary trunk temporarily associated with the line of a calling subscriber, a traveling switch associated with said trunk, an intermediate trunk temporarily associated with said primary trunk, switch controlling mechanism temporarily associated with said intermediate trunk, controlling means at said primary trunk effective to release said intermediate trunk from association with said primary trunk prior to the association of said intermediate trunk with said switch controlling mechanism and thereafter disabled until the initial operation of said traveling switch.

17. A telephone call distributing system comprising a group of call receiving units, a call signal for each of said units, means for causing the display of said call signals, manually actuated means for excluding any desired units from service, automatically actuated means for temporarily disassociating certain units from association with said group, and indicating means effective in case of the simultaneous disassociation of all units not excluded from service.

18. A telephone call distributing system comprising calling lines, a group of call receiving units, a call signal for each of said units, means for causing the display of said call signals, manually actuated means for excluding any desired units from service, automatically actuated means for temporarily disassociating certain units from association with said group, and indicating means actuated responsive to a calling line in case of the simultaneous disassociation of all units not excluded from service.

19. In an automatic telephone system, subscribers' lines, a plurality of sequen-

- 5 initially operated switches for building up a connection extending between a calling and a called line, operator actuated means for directly controlling the operation of said switches, a supervisory relay associated with the initially operated one of said switches, and means for excluding said relay from circuit for a definite interval following the operation of said operator actuated means.
- 10 20. In an automatic telephone system, a group of traveling switches, a normally open contact on each of said switches, means for closing said contact on actuation of the associated switch, and a registering device actuated on simultaneous closure of all of said normally open contacts.
- 15 21. In an automatic telephone system, a selector switch mechanism comprising waiting contacts, traveling contacts adapted for engagement therewith, driving mechanism for advancing said traveling contacts, restoring means for said traveling contacts, a release relay controlling said restoring means, and an energizing circuit for said release relay completed independently of said traveling contacts and only following the advance thereof.
- 20 22. An automatic telephone system comprising a group of circuit units, a selection initiating relay for each of said units, automatic mechanism operative responsive to the energization of any one of said relays to select the associated unit, a guarding circuit common to said units maintained closed during the period while any of said relays are energized, a normally closed circuit controlled by said guarding circuit maintained closed only while said guarding circuit is interrupted, and mechanism actuated responsive to an abnormal period of interruption of said normally closed circuit to cause an alarm signal.
- 25 23. An automatic telephone system comprising a group of circuit units, a selection initiating relay for each of said units, automatic mechanism operative responsive to the energization of any one of said relays to select the associated unit, a guarding circuit common to said units maintained closed during the period while any of said relays are energized, a normally closed circuit controlled by said guarding circuit maintained closed only while said guarding circuit is interrupted, and mechanism actuated responsive to an abnormal period of interruption of said normally closed circuit following the initiation of a selective operation to cause the initiation of an alternative selective operation.
- 30 24. In a telephone exchange system a plurality of trunks, automatic switches for extending said trunks to the lines of called subscribers, means for connecting said trunks with the lines of calling subscribers, manually actuated means for directly controlling the operation of said switches, automatic means for connecting said manually actuated means with said trunks, a call signal displayed upon connection of said manually actuated means, and manually controlled means for preventing the display of said signal effective only during the connection of said manually actuated means.
- 35 25. In a telephone call distributing system a group of trunk lines and a selection-initiating circuit, a trunk selecting mechanism associated therewith comprising a calling signal, a group of relays, switch contracts momentarily actuated to complete energizing circuits for certain predetermined relays of said group, a locking circuit established following actuation of relays so energized, means operated on completion of said selection-initiating circuit to cause the actuation of said switch contacts, other similar trunk selecting mechanisms, means for completing said selection-initiating circuit, and means, effective in case said selection-initiating circuit remain completed for an abnormal period, to substitute one of said other trunk selecting mechanisms for the first mentioned trunk selecting mechanism.
- 40 26. In a telephone exchange system, a selection-initiating circuit, a circuit selecting mechanism associated therewith comprising a group of relays, switch contacts momentarily actuated to complete energizing circuits for certain predetermined relays of said group, a locking circuit established following actuation of relays so energized, means operated on completion of said selection-initiating circuit to cause the actuation of said switch contacts, other similar circuit selecting mechanisms, means for completing said selection-initiating circuit, and means, effective in case said locking circuit fail of establishment, to substitute one of said other circuit selecting mechanisms for the first mentioned circuit selecting mechanism.
- 45 27. In a telephone exchange system, a selection-initiating circuit, a circuit selecting mechanism associated therewith comprising a group of relays, switch contacts momentarily actuated to complete energizing circuits for certain predetermined relays of said group, a locking circuit established following actuation of relays so energized, means operated on completion of said selection-initiating circuit to cause the actuation of said switch contacts, other similar circuit selecting mechanisms, means for completing said selection-initiating circuit, and means, effective in case of prolonged actuation of said switch contacts, to substitute one of said other circuit selecting mechanisms for the first mentioned circuit selecting mechanism.
- 50 28. In a telephone exchange system, an impulse controlling device comprising a plurality of sets of keys controlling elec-

1,252,974

61

1,262,974
61
A system of electrical points, circuits extending from said points to the keys of a plurality of sets in talking conductors, a switch for interrupting said circuit, and means effective upon interruption of said circuit to prevent the subsequent selection of said trunk line.

29. An automatic telephone system comprising traveling switches, rows of keys corresponding to the several digits of the call numbers of said system the keys in each row corresponding respectively to the several numerals used as digits in said call numbers, means for causing the advance of said switches to points corresponding to certain keys actuated in the several rows, and means automatically actuated prior to the actuation of said keys for releasing any keys previously actuated in certain rows.

30. An automatic telephone system comprising traveling switches, rows of keys corresponding to the several digits of the call numbers of said system the keys in each row corresponding respectively to the several numerals used as digits in said call numbers, means for causing the advance of said switches to points corresponding to certain keys actuated in the several rows, means effective if there be no keys actuated in certain of said rows whereby said switches are advanced to certain predetermined positions, and means automatically actuated prior to the actuation of said keys for releasing any previously actuated keys in certain rows, whereby call numbers having less than the maximum number of digits may be employed in said system.

31. In a telephone exchange system, an impulse controlling device comprising a set of keys for each digit of the maximum number assigned to a line in the system, electrical points controlled from said keys, circuits extending from said points to corresponding keys of a plurality of such sets of keys in the same order, and circuits extending to the keys of the units digit in a different order.

45 32. In a telephone exchange system, an impulse controlling device comprising a set of keys for each digit of the maximum number assigned to a line in the system, electrical points controlled from said keys, circuits extending from the first electrical point to the first key of a plurality of such sets of keys and to the last key of the set of such keys individual to the units digit.

50

33. In an automatic telephone exchange system, a trunk line extending by a pair of talking conductors to a traveling switch, means for selecting said trunk line, a normally closed circuit including one of said talking conductors, and means effective upon interruption of said circuit to prevent the subsequent selection of said trunk line.

34. In an automatic telephone exchange system, a trunk line extending by a pair of talking conductors to a traveling switch, means for selecting said trunk line, a nor-

8,974,611 *Telephone line to subscriber with plurality of trunk lines, including a plurality of trunk lines, each having a plurality of conductors, a plurality of conductors being connected in a mally closed circuit including one of said talking conductors, a switch for interrupting said circuit, and means effective upon interruption of said circuit to prevent the subsequent selection of said trunk line.*

35. A telephone exchange system comprising a calling line, a selector switch, primary selecting apparatus for associating said line with said switch, secondary selecting apparatus actuated responsive to the operation 75 of said primary selecting apparatus, a called subscriber associated with said selector switch, means under control of said called subscriber for restoring said selector switch, and means to prevent such restoration from 80 causing the actuation of said secondary selecting apparatus.

36. An automatic telephone exchange system comprising a calling line, a selector switch associated therewith, a trunk line extending by a pair of talking conductors between said switch and a second selector switch, a third conductor, a magnet for said second selector switch included in circuit between one of said talking conductors and said third conductor, means for interrupting the circuit of said magnet on restoration of said selector switch, and a restoring circuit for said second selector switch established on deenergization of said magnet. 90 95 85

37. An automatic telephone exchange system comprising a calling line, a selector switch associated therewith, a trunk line extending by a pair of talking conductors between said switch and a second selector switch, a called line associated with said second selector switch, means including one of said talking conductors for directly controlling the operation of said second selector switch, a release circuit including said one conductor under control of the called line, and means controlled by said release circuit for restoring said selector switch. 100 105

38. An automatic telephone exchange system comprising a calling line, a selector switch associated therewith, a trunk line extending by a pair of talking conductors between said switch and a second selector switch, a called line associated with said second selector switch, means including one of said talking conductors for directly controlling the operation of said second selector switch, a release circuit including said one conductor under control of the called line, and means controlled by said release circuit for restoring said second selector switch.

39. An automatic telephone exchange system comprising a calling line, a selector switch associated therewith, a trunk line extending by a pair of talking conductors between said switch and a second selector switch, a called line associated with said second selector switch, means including one of said talking conductors for directively con- 130

trolling the operation of said second selector switch, a release circuit including said one conductor under control of the called line, and means controlled by said release line, and means controlled by said release 5 circuit for restoring both selector switches.

40. An automatic telephone exchange system comprising a calling line, a selector switch associated therewith, a trunk line extending by a pair of talking conductors between said switch and a second selector switch, a called line associated with said second selector switch, a release circuit including one of said talking conductors, a controlling circuit controlled by the called line including the other of said talking conductors, an inductive winding included in the last mentioned circuit, and restoring means for said selector switch controlled by said winding.

20 41. An automatic telephone exchange system comprising a calling line, a selector switch associated therewith, a trunk line extending by a pair of talking conductors between said switch and a second selector switch, a called line associated with said second selector switch, a release circuit including one of said talking conductors, a controlling circuit controlled by the called line including the other of said talking conductors, an inductive winding included in the last mentioned circuit, restoring means for said selector switch controlled by said winding, and means controlled by the calling line for also controlling said restoring means.

35 42. A telephone exchange system comprising a calling line, an operator's cord circuit and plug, a spring jack adapted for association therewith, a selector switch associated with said spring-jack, a trunk line extending by a pair of talking conductors from said selector switch to a second selector switch, a called line associated with said second selector switch, a release circuit including one of said talking conductors, a controlling circuit controlled by the called line, including the other of said talking conductors, an inductive winding included in the last mentioned circuit, a supervisory signal associated with said plug, and means 50 under control of said winding for controlling the display of said signal.

43. A telephone exchange system comprising a calling line, an operator's cord circuit and plug, a spring-jack adapted for association therewith, a selector switch associated with said spring-jack, a trunk line extending by a pair of talking conductors from said selector switch to a second selector switch, a called line associated with said second selector switch, a release circuit including one of said talking conductors, a controlling circuit controlled by the called line including the other of said talking conductors, an inductive winding included in the last mentioned circuit, restoring means

controlled by said winding for restoring said selector switch, and means controlled by said plug for also controlling said restoring means.

44. A telephone exchange system comprising a calling line, an operator's cord circuit and plug, a spring-jack adapted for association therewith, a selector switch associated with said spring-jack, a trunk line extending by a pair of talking conductors from said selector switch to a second selector switch, a called line associated with said second selector switch, means including one of said talking conductors for directly controlling the operation of said second selector switch, a release circuit including said one conductor under control of the called line, restoring means controlled by said release circuit for restoring said selector switch, and means controlled by said plug for also controlling said restoring means.

45. In a call distributing system a plurality of calling lines, a plurality of call receiving units, automatic means for extending any one of said lines to any one of said units, and differentiating means associated with the said units actuated on extension to said units of predetermined ones of said plurality of lines.

46. In a call distributing system a plurality of calling lines, a plurality of call receiving units, automatic means for extending any one of said lines to any one of said units, differentiating means associated with the said units actuated on extension to said 100 units of predetermined ones of said plurality of lines, and indicating means controlled by said differentiating means.

47. In a call distributing system a plurality of calling lines, a plurality of call receiving units, automatic means for extending any one of said lines to any one of said units, differentiating means actuated on extension to said units of predetermined ones of said plurality of lines, automatic switching mechanism for extending said calling lines to connection with called lines, means associated with said units for exercising directive control of the operation of said switching mechanism, and means controlled 110 by said differentiating means for modifying said directive control.

48. In a telephone exchange system, an impulse controlling device comprising a set of keys for each digit of the maximum number assigned to a line in the system, electrical points controlled from said keys, and a circuit extending from the last electrical point to the last key of each set other than the set assigned to the units digit and to the 125 next to the last key of the set assigned to the units digit.

49. In a telephone exchange system, calling lines, call receiving units arranged in related groups, connecting devices associated 130

with each call receiving unit adapted when operated to associate a calling line with such call receiving unit, a common start circuit for said connecting devices over which said connecting devices are selected and started into operation, operator-controlled means common to a group of call receiving units for temporarily removing the connecting devices of all of the call receiving units of the group from association with said common start circuit.

50. In a telephone exchange system, calling lines, call receiving units arranged in related groups, connecting devices associated with each call receiving unit adapted when operated to connect a calling line to such call receiving unit, a common start circuit for said connecting devices over which said connecting devices are selected and started into operation, means for removing the connecting devices of a call receiving unit from association with such start circuit when such connecting devices are operated, means for also removing the connecting devices of other call receiving units of the same group from association with said start circuit, an operator-controlled means for again asso-

ciating the connecting devices of all of the call receiving units of a group except those in use with said start circuit.

30

51. In a telephone exchange system, calling lines, a plurality of call receiving units arranged in related groups, connecting means individual to each call receiving unit, adapted when operated to connect that call receiving unit to a calling line, a start circuit for said connecting means extending to said groups of call receiving units in series, branches of said start circuit extending to the call receiving units of a group in series, 40 and means rendered operable by the operation of the connecting means of a call receiving unit to extend the main start circuit of the next group of call receiving units and also to extend the branch of the start circuit 45 individual to such group to the next call receiving unit in the group.

In testimony whereof, I affix my signature in the presence of two witnesses.

HARRY G. WEBSTER.
